UNITED STATES PATENT OFFICE.

JOSEPH PINEL, OF ALTRINCHAM, ENGLAND.

TYPE CASTING AND COMPOSING MACHINE.

SPECIFICATION forming part of Letters Patent No. 786,313, dated April 4, 1905.

Application filed February 12, 1903. Serial No. 143,126.

To all whom it may concern:

Be it known that I, JOSEPH PINEL, of Altrincham, whose post-office address is Grove Villa, Manchester Road, Altrincham, in the 5 county of Chester, England, have invented certain new and useful Improvements in Type Casting and Composing Machines; and I do hereby declare the following to be a full, clear, and exact description of the invention, such 10 as will enable others skilled in the art to which it appertains to make and use the same.

The present invention relates to improvements in machines adapted to act either as ordinary type-casting machines controlled as to 15 output by the man in charge or as automatic type casting and composing machines. The latter are generally referred to as "machines for casting type" in the order of composition, and their action is controlled by perforated 20 strips or ribbons known as "mechanical controllers." The tachytype, the Goodson, and the monotype machines are well-known representatives of this class of machine. The improved controller, which must be used with 25 the improved automatic machine described in this specification, is no part of the present invention. It forms the subject of Letters Patent No. 744,230, dated November 17, 1903.

It is necessary to describe the improved automatic machine before describing the improved ordinary type-casting machine, because the latter is the former shorn of some 30 of the organs which contribute to its automaticity—rather is the former a development 35 of the latter; but before proceeding to describe either there must be a description of the improved controller. In either representative machines above mentioned the matrices are arranged in a square matrix-carrier, 40 which must be moved in both of two directions each at a right angle with the other to make the matrix for the desired type-face register with the mold for the type-body, and two perforations in the controller are necessary—one to effect each of these motions. In 45 the improved controller the number of perforations for any character-matrix may vary from unity upward. Further, as the improved matrix-carrier may have and preferably has more than one font in it at a time

the controller carries font-changing perforations distributed along it, one such perforation being associated with each transverse row of perforations demanding a change of font from the normal one. There are the 55 usual spacing or justifying and feeding perforations and proof of the composition.

The controller is carried by two rollers—one to pay it out and the other to take it up. It is fed past an air-chamber, so as to close 60 one side thereof by its unperforated portions and to establish communication between the chambers and respective outlets by its perforations, the air-chamber being kept charged with air under pressure. 65

The matrix-carrier is a drum capable of rotation about its vertical axis through a longer or shorter arc for change of character and of vertical motion in either direction for change of font. The fonts are arranged in tiers, 70 each column of matrices carrying the same character, or nearly so.

Each matrix is a separate piece, and all the pieces of a column are held to the carrier by being strung upon a vertical rod or by equivalent means. The backs of the columns bear upon the periphery of the central drum of the matrix-carrier and are separated into groups by vertical bars which carry the space-formers and the second projections above mentioned, the drum being completed by a top and bottom disk, which hold the vertical rods and bars firmly in position. 75

The matrix-carrier fits upon a central and vertical axle and turns with it, but from which 80 it can be easily moved and another equipped with a different set of fonts substituted. It can also slide freely up and down the said axle for the purpose of changing font, which change is effected by the means described farther on. 90

The controller-feeding device consists of a roller having two sets of teeth adapted to engage in the feeding-perforations in the margins of the controller. It is actuated with a step-by-step motion, so as to feed the controller one set of perforations—*i. e.*, one character—at a time. To effect this, the matrix-carrier or an arm projecting from it forces a projection on a certain lever against a bell-crank lever each time it moves toward the 100

mold. The rock of the bell-crank lever actuates a pawl and ratchet-wheel in gear with the feed-roller against a returning-spring.

Each time that the controller stops, the air 5 rushes through the perforations representing the respective character and a corresponding number of outlets from the air-chamber, they being tubes leading the blasts to as many cylinders. Each cylinder is provided with its 10 own piston, and the end of the piston-rod is projected from the respective cylinder to rock a lever. The levers so rocked move as many of a series of six (the number of longitudinal 15 rows of perforations in the controller) parallel slides, so as to make them present a series of holes in them corresponding in position to the perforations on the controller to a lever carrying similarly-positioned studs. There 20 are as many of these last-mentioned levers as there are columns of matrices in the matrix-carrier, and opposite them there is a horizontal cylinder constantly turning in suitable bearings in the machine-frame, to which each lever 25 can be automatically rocked. There are arranged on the periphery of this cylinder and in echelon a series of projections respectively opposite the said levers, each of which is notched to engage with its lever, the notches standing in extensions of the levers curved in 30 their own planes. The cylinder is connected by suitable miter-gearing to the axle of the matrix-carrier. Accordingly, when the slides are adjusted to present a combination of holes corresponding with the combination of 35 perforations in the controller then in the air-chamber the respective rocking lever carrying studs corresponding in position and number with the adjusted holes in the slides will be pulled toward the cylinder until its notch 40 engages the respective projection thereon, the lever being allowed to rock far enough to effect such engagement by the entrance of its stud or studs into the said holes in the slides. Such an engagement takes place only when 45 the matrix-carrier has completed the arcual motion necessary to bring the desired matrix opposite (but not up to) the mold and forthwith stops the carrier. Thus the presence of a perforation in the controller means the pro- 50 trusion of a piston-rod and that this rod is the first in a combination of elements of which a rocking lever is the last.

Each time that a dwell of the controller in the air-chamber presents a perforation for 55 change of font air rushes through the same perforation and a flexible tube into a cylinder and makes the piston of the latter protrude the end of its piston-rod. There are as many sets of tubes, cylinders, and piston-rods as 60 there are fonts in the matrix-carrier less one. The cylinders are fixed in a block to the frame of the machine and are set in a column or in echelon in the line of the travel of the matrix-carrier up to the mold. At a certain 65 point in that travel the vertical arm of a bell-

crank lever pivoted upon the matrix-carrier carriage is stopped by the protruded piston-rod end, the consequent upward rock of the opposite arm of the said lever raising the carrier more or less, according to the position 70 of the protruded piston-rod end, thereby bringing the required font into the plans of the mold. The cylinder-block must have a motion of its own in order that the protruded piston-rod may cease to act as a stop as soon 75 as the matrix-carrier has been raised and engaged with a fixed stud projecting from the mold.

The mold is movable from the casting to the trimming position and from the latter to the 80 ejecting position and back again to the casting position upon a platform which provides a bottom for the mold-cavity. Its terminal positions are established by adjustable stops. These motions take place between the guides, 85 the mold being kept in working contact with the platform by spring-pressure suitably applied upon the top of it.

Each matrix carries a projection adapted to the mold-cavity for the purpose of adjusting 90 it for set width of type-body. Such a projection acts as follows: As the matrix-carrier comes up to the mold the projection acts as a push-piece against the vertical arm of a bell-crank lever and rocks the horizontal arm up 95 against the force of a returning-spring. The end of this horizontal arm raises a lever having an adjustable fulcrum, and the lever raises a slide the foot of which, in conjunction with the foot of the second slide, bounds the 100 mold-cavity above the type, the platform bounding it below. Thus the adjustment of the fulcrum of the lever modifies the effect of the matrix projection both as to thickness of type-body setwise and to the width in the 105 same direction of one side bearing. The two slides just mentioned—first or principal and second—both reciprocate in suitable guides and are provided with a suitable returning-spring. These slides stand edge on in the 110 same plane, the principal one behind the other, and are connected together and yet capable of independent motion.

The mold is adjusted for change of type-body in the direction from back to belly or 115 to make the type self-leading by substituting another pair of slides for those in the mold.

The mold as a whole is provided with a suitable set of ports through which a circulation of water is maintained to keep it sufficiently cool. Further, the position of the type-face, as between back and belly of type-body, is adjustable by making the mold register with the matrix as much to either the right or the left of the position of normal registration. 125

The metal-pot is adjustable by a screw up to the mold-gate for each change of font.

The piston is free to make the down or working stroke at the moment when the matrix is pressed up to the mold by the follow- 130

ing means: The reciprocating frame that carries the matrix-carrier and the mechanism for raising or lowering it carries an arm pivoted on its rear side and projecting therefrom. The motion of the matrix-carrier up to the mold makes the nose of this arm push the upstanding arm of a three-armed bell-crank lever backward against the pull of its returning-spring. At a predetermined moment the arm leaves the lever, whereupon the latter is pulled back smartly by its spring, its opposite arm pushing up a vertical rod connecting it to the pump-lever and rocking the latter to put the piston through its working stroke.

15 The galley is concave to the front in order that it may deliver its column of matter onto any horizontal surface arranged as a continuation of it. A bar extending from top to bottom of it is capable of lateral adjustment in

20 guides in the galley-frame, according to length of line. The line as it gathers in the horizontal portion of the type-race stands on a movable line-support and pushes a line-stop before it. The arrival of the last letter of the

25 line onto the line-support makes the first letter push the line-stop up to an arm depending from the front end of a rock-shaft turning in a piece supported upon the galley-top and capable of lateral adjustment in a suitable

30 guide in the galley. The rear end of the rock-shaft has a like depending arm terminating in a fork which engages a clutch adjustable lengthwise upon a shaft parallel with the galley-top and behind it. This clutch is adapted to engage a constantly-rotated gear. The shaft carries a cam likewise adjustable lengthwise on it, as well as a device to withdraw the line-support. This device may consist of one or more disks, each carrying a pair of radial

40 studs adapted to engage with corresponding teeth or ridges adjustable or fast on the adjacent edge of the line-support. The withdrawal of the latter is followed by the engagement of the cam with a depressor, which is immediately pushed down against its returning-springs, thereby forcing the line down into the galley. As soon as this line has cleared the line-stop the latter, as well as the line-support, are automatically returned to their original positions, while the clutch is also automatically opened, thereby stopping the rotation of the shaft. The depressor is fitted with a foot capable of a short vertical motion on suitable guides, there being springs between

45 the depressor and it. The object of this foot is to enable the depressor to automatically adjust its action to lines of different sizes from back to belly of the type-bodies. The nose of this foot is rounded underneath, so that the first type fed into the horizontal part of the type-race may easily lift it to get under it, and the line-stop slide is slotted to let the depressor-foot pass down through it.

50 The return of the line-stop is prevented from forcing a type past the spring-detents

by the following means: A frictional detent-lever is pivoted on a fixed axis outside the slide that carries the line-stop, its nose standing on the side of the first-mentioned depending arm and its returning-lever opposite to that on which stands the line-stop itself. The opposite end of this detent-lever is pressed outward by a spring to keep the nose of it pressed operatively against the line-stop slide, said opposite end standing between the galley and the returning-lever and in contact with it, their contacting faces being beveled to the same angle, so that the nose of the detent-lever locks the line-stop slide at the end of each type-feed, and when the line is finished the rock of the swinging arm rocks the returning-lever of the latter, its beveled face rocking the detent-lever away from the said slide and leaving the line-stop slide free. The first line to be depressed is received by a rising and falling shelf as long as the adjusted width of the galley. This shelf is suspended from a cord which is led over pulleys to the back of the machine and is fitted with automatic detents adapted to hold it at any desired height. These pulleys are carried by an arm adjustable laterally on the galley, so that the cord shall always pull from the middle of the shelf. The opposite end of the cord is made fast to and wound upon a roller turning in suitable bearings in the back frame of the machine. The axle of this roller carries a spur-pinion gearing with a toothed sector fast on a shaft parallel with the roller, from which shaft depends an arm fast to it and carrying a weight adjustable thereupon to act as a counterpoise to the gradually-increasing weight of the galley, the plane on which the arm rocks being at right angles with the width of the galley. The shelf can be withdrawn from the bottom or at sundry levels above that, a handle and suitable openings in the galley sides being provided to facilitate or allow of such withdrawal. The counterpoise has a ratchet-detent combined with it, which is to be released by the operator, so as to allow of the shelf being returned to the top of the galley gradually, and also a stop to prevent it swinging too far to the front.

Referring to the accompanying drawings, which are to be taken as part of this specification and read therewith, Figure 1 is a plan of a short length of the improved controller duly justified and therefore ready for the casting-machine. Fig. 2 is a development of the periphery of the matrix-carrier. Fig. 3 is a diagram showing the transverse rows of perforations which correspond, respectively, with the columns of characters in the matrix-carrier and including a series of font-changing perforations and one of spacing-perforations. Figs. 4 and 5 together constitute a front elevation of the casting-machine, but omitting the matrix-carrier and some of the rocking arms. Figs. 6 and 7 together constitute a rear elevation

of the same, omitting the metal-pot and pump. Figs. 8 and 9 together constitute a plan of the same, omitting the metal-pot. Fig. 10 is a plan of the metal-pot and pump. Fig. 11 is a transverse section on line 11 11 of Figs. 4, 5, 7, and 8, including the metal-pot and pump. Fig. 12 is a sectional elevation on line 12 12 of Fig. 4 looking at it from the left hand. Fig. 61 is an enlarged front elevation of the type-race. Fig. 62 is a partial plan of Fig. 61, including additional details. Fig. 63 is a perspective detail of Fig. 62. Fig. 64 is a sectional plan on line 64 64 of Fig. 61. Fig. 65 is a perspective view of a part of the 85 mold. Fig. 66 is a section on line 66 66 of Fig. 61. Fig. 67 is a section on line 67 67 of Fig. 66. Fig. 68 is a perspective view of a type showing its position in the mold. The particular type is a "q." Fig. 69 is a perspective view of the driving connections of the machine. Fig. 70 is a synchronical diagram of the various operations of the machine.

To prevent any misunderstanding of the presence of Figs. 1 and 3, it is repeated that 95 the improved controller illustrated thereby forms no part of the present invention. They are introduced to facilitate a correct understanding of the relation between the said controller and the improved matrix-carrier.

Referring first to Fig. 2, 1 2 3 4 5 6 are the six tiers of matrices in a six-font machine. There are forty columns 7 of character-matrices, all visible in the figure, and ten plates 8, carrying devices for adjusting the mold for 10 spaces.

Referring to Figs. 1 and 3, 9 9 are the two rows of feeding-perforations. These are as heretofore and need no further description. 10 10 are the six imaginary parallel lines running lengthwise of the controller. 11 11 are the perforations in transverse rows, each perforation on one of the lines 10. The number of perforations in any row is variable from unity upward, and each row controls one particular column 7 of character-matrices or blank matrices in the sense that when that transverse row of perforations stands in operative position in the casting-machine the matrix-carrier is turned about its vertical axis until the respective column in the periphery of the said carrier is opposite the mold for the body of the next type to be cast. The means by which the said transverse row of perforations in the controller turns the matrix-carrier may be of any suitable kind. Thus if it is the transverse row 11 on the extreme left of Fig. 3 that is standing in operative position in the casting-machine the matrix-carrier is turned until that column 7 which is shown on the ex- 11 12 13

treme left of Fig. 2 is brought opposite the mold for the body of the next type.

The above is true for a matrix-carrier adapted to be turned about its vertical axis whether such carrier has only a single font—say the tier 1 of Fig. 2—or several fonts arranged in tiers, as the six tiers 1 to 6 of the said figure. The improved controller is adapted to change the font at any moment in use in the casting-machine to the one which the matrix-carrier is required to next present to the mold of the machine by a series of perforations distributed upon imaginary parallel lines 12 to 16. (See Fig. 3.) There are as many of these imaginary lines as there are fonts in excess of unity, because it is self-evident that when there is only one font it requires neither elevation nor depression. Thus as there are six fonts in the matrix-carrier shown in Fig. 2 there are five parallel lines 12 in the controller, (marked, respectively, 12, 13, 14, 15, and 16.) There is one of these font-changing perforations shown in Fig. 3 on each of these five lines, they being marked, respectively, 17, 18, 19, 20, and 21, and are alined transversely thereon with the respective transverse row of perforations 11. The effect of a font-changing perforation is to raise or lower the matrix-carrier from the position it may occupy at any given moment to the one which will place the desired font in the plane of or opposite to the mold. Thus there being no font-changing perforation against the transverse row of perforations 11 on the left of the one against which the perforation 17 stands the matrix-carrier is holding the top tier or font 1 opposite the mold; but as soon as the next transverse row of perforations 11 gets into operative position (the direction in which the controller moves through the machine is indicated by the arrows of Figs. 1 and 3) the perforation 17 has the effect of raising the matrix-carrier through a distance equal to the thickness of one tier—that is to say, it will place the tier 2 in the position out of which it at the same time moves the tier 1—and so with each of the other font-changing perforations 18 to 21. The means by which a font-changing perforation alters the position of the matrix-carrier in a vertical sense may be of any suitable kind, but is preferably of the same kind as the means by which a transverse row of perforations 11 turns the matrix-carrier.

22 22 are space-perforations and coöperate with the blank matrix-plates 8 already mentioned. Any one of these perforations brings the respective column of blank matrices opposite the mold. If it be desired, a font-changing perforation may be combined with any space-perforation 22.

23 (see Fig. 1) is the usual proof.

The transverse rows of perforations in Fig. 1 stand for (reading from the left or leading end) the following line: an em quad, "PLINE," 65 an en quad, "Fonderie," a space, "Typograph-

ique," a space, "Dijon," a space, "1902," four em quads and a space, fifty in all. The first em quad is cast from tier 1; but the next character is in the third tier, 3, so that there is a font-changing perforation 18 alined with the respective perforations 11. The next four characters are small capitals, which are all in tier 5, so that there is a font-changing perforation 20 alined with the respective rows of perforations 11, and so on for the "F" of "Fonderie," the "T" of "Typographique," the five characters of "Dijon," the comma immediately following them, and the figures "1902."

Returning to the subject-matter of the present invention, the improvements in type casting and composing machines, the first feature of it to be dealt with is—

The controller-carrier.—This is shown in Fig. 5. It is detachable from the casting-machine. 24 is the controller presenting itself edge on. It is carried, as heretofore, by two drums 25 26, each supported in its own bearings (not shown in the figure) in a pair of slotted standards 27, (the front one of which is omitted from the figure,) standing up from a flat plate 28, which is held down by set-screws 29 upon a second and larger plate 30, adapted, by means of angled edges 31 31, to engage in corresponding grooves in the frame 32 of the machine. The object of the detachability of the controller-carrier is to allow of its being replaced by the controller perforating or "keyboard" machine, as it is frequently called, and which latter is for that purpose mounted upon a substitute plate adapted to engage in the above-mentioned grooves. This substitute plate will be of the same size and shape as the larger plate 30, above described, in order that it may fit in the same way into the grooves in the machine-frame 32. Thus one plate, 30, will have the controller 24 and the controller-drums 25 26 and standards 27 mounted upon it, as shown in Fig. 5, while the substitute plate will have only the keyboard-machine on it. The advantage of this detachability is that if a controller is ready for the casting-machine by the time the man in charge of the latter is ready to use it therein it can be at once wound upon the feed-drum 26 and so used, whereas if there is no controller ready the plate 30, with the standards 27 and drums 25 26, can be detached from the machine-frame and the plate that carries the keyboard-machine slid into the said grooves, thereby placing the keyboard-machine in operative combination with the casting-machine, because the controller will be fed from the latter into the controller-feed (described farther on) direct.

Controller-feed.—This is shown in Figs. 4, 8, 20, 21, 22, 23, 24, and 27. 33 is the traversing drum, fast on the spindle 34, turning in standards 35 35, fast to the frame 32. 36 is a slide reciprocating in fixed guides 37 37. The main purpose of this slide and the means by which it is reciprocated will be found de-

scribed farther on. Each time that this slide is moved to the rear a finger 38, carried by it and projecting to the right, comes into contact, as shown in Fig. 8, with the top end of 5 a lever 61, fulcrumed upon the main shaft 62, thereby making the said lever rock up the left arm of a bell-crank lever 39, turning on a fulcrum 40. The other or forwardly-extending arm of the lever 39 stands between a pair of 10 blocks 41 42, adjustable on the pawl-carrier 43, (seen best in Fig. 22,) sliding in a guide 44, fast on the machine-frame 32 and embracing the spindle 34 by means of a lateral slot 45, the said spindle serving as a second guide. 46 is 15 the pawl of the carrier 43, 47 its pivot, and 48 its spring, the latter holding it in contact with the ratchet-wheel 49, loose on the spindle 34 and having fast to its side a crown-gear 50, which drives the miter-gear 51, fast on the 20 rear end of the drum 33, through a miter-pinion 52, turning on an upright pin 53, fast in the base of the standards 35. The traversing drum 33 carries feed-pins 54, projecting from 25 its periphery at equal distances apart near its ends and at a proper distance lengthwise of the drum to engage the pairs of feeding-perforations 9 in the controller 24. 55 is a non-return pawl pivoted on the rear standard and kept in contact with the ratchet-wheel 49 by 30 a spring 56. 57 is a bar-spring fast to the frame 32 and bearing against the left side of a stud 58, fast to the pawl-carrier 43. When the feed-drum 33 is at rest, a longitudinal pair of feed-pins 54 is engaged in a pair of feed- 35 perforations 9 in the controller 24. The above-described motion of the slide 36 moves the pawl-carrier 43 to the left, and the controller 24 is consequently moved the distance between two adjacent transverse rows of perforations 40 11, measuring from center to center, the non-return pawl 55 locking the traversing drum 33. As soon as this has been done, the finger 38 is withdrawn from the bell-crank lever 39, and the spring 57 returns the latter and the 45 pawl-carrier 43 to their original positions. 59 is a roller turning in the standards 35 to keep the controller 24, then traveling in the direction indicated by the arrows in Figs. 4 and 5, in the plane of the coöperating face of the air- 50 chamber (described in the next section) after it has passed the same, and 60 is a second roller turning in the same standards to keep the controller 24 in contact with a sufficiently long arc of the said drum 33. The take-up drum 55 25 is provided with suitable means for rotating it to make it wind up the controller passing to it from the roller 60.

Matrix-carrier.—For a single font it consists of a disk capable of motion about its vertical axis for change of character and a locking-ring to perfect the register of the selected matrix with the mold for the body of the type to be cast by preventing accidental motion of the matrix-carrier about its axis. For more 60 than one font it consists of a drum carrying

the different fonts in tiers superposed one above the other, the drum being capable of motion about its vertical axis for change of character and of vertical motion in either direction along that axis for change of font and 70 having combined with it as many locking-rings as it has fonts, each locking-ring coöperating with the respective font to perfect the register of the selected matrix thereof with the above-mentioned mold and in the way 75 above mentioned. Figs. 1 to 3 are drawn to illustrate the use of a six-font matrix-carrier. The matrix-carrier 63 is for that reason detailed as a six-font one. It is shown in its entirety in Figs. 11, 19, and 69 and the details of it in Figs. 14 to 18. The body of the matrix-carrier 63 consists of the U-shaped annulus 64, having a flange 65 projecting for a certain distance from the closed bottom of it, the top plate 66 screwed down upon it by 80 screws 67 and projecting beyond it for the same distance as the flange 65. Each tier of matrices comprises all the matrices of one font, and the several tiers are superposed in such a way that any one column shall comprise the same character. This will be clear from an inspection of the development of the periphery of the matrix-carrier in Fig. 2. The top tier 1 comprises the matrices of the lower-case Roman font. The second tier 2 85 comprises those of the lower-case italic. The upper-case Roman font is in the third tier 3, the upper-case italic font in the fourth tier 4, small capitals in the fifth tier 5, and figures in the sixth tier 6. The matrices left blank 90 may be utilized as sorts-matrices. Under no circumstances does the setway width of any font or sorts type exclude it from the improved matrix-carrier, for the simple reason that each matrix in it has its own device for 95 adjusting the set width of the corresponding type-body—viz., the respective projection 78, described farther on. There are ten sets of devices for adjusting the mold for that number of different sizes (setway widths) of spaces, 100 one set on each of the plates 8; but as each plate 8 carries its adjusting devices at one end of it and as all the ten sets occupy only one tier it follows that there is room in each plate 105 for five additional matrices. As shown in 110 Fig. 15, each character-matrix is a nearly rectangular block 68, having its formative cavity 69 for the type-face in its outer end. All the matrices of a column are threaded upon an upright rod 70, the top end of which fits into 115 a hole 71 in the top plate 66, while its bottom end fits into a hole 72 in the flange 65. A column of matrices fills the vertical space between the flange 65 under it, and the plate 66 over it backs up against the outer face of 120 the annulus 64, which serves to support each matrix independently of the other devices for holding it steady against the pressure exerted in the act of making it fit metal-tight 125 up against the mold for the type-body. By 130

the side of each column there stands a vertical plate 73, likewise fitting up to the top plate 66 above it and the flange 65 below it and supported by the annulus 64. It is further held in position by pins 74 75, projecting from each end of it and which engage, respectively, in a hole 76 in the top plate 66 and in an opposite hole 77 in the flange 65. A plate 8 is held to the periphery of the annulus 64 by screws 79. To add to the solidity and rigidity of the matrix-carrier, it is preferred that four (or about that number) columns of matrices 68, projections 78, and one plate 8 should fit in between and be supported laterally by two vertical ridges 80 on the annulus 64. 78 78 are projections standing out radially from each plate 73, there being as many projections from a plate as there are matrices in a column. Each projection is rectangular in vertical section, but differs from the others more or less in length and coöperates with its respective matrix 68 to adjust the mold for the set width of the body of the type. Instead of the projections 78 and their supporting-plates 73 there may be used screw-pins passed radially through the annulus 64, in which case the columns of matrices will fit close up to each other or to an adjoining plate 8, each matrix side being grooved to fit over the coöperating screw-pin.

Each of the before-mentioned plates 8 is provided with two projections 81 82 near the top end. Each of these two projections is rectangular in vertical section. They differ both in length, as well as in function. A projection 81 enters the mold to adjust it for the setway width of the space to be cast in it, which space will be of the same height as the body of a type cast against a matrix 68. Experience has shown that the tops of such spaces are high enough to take ink in the printing-machine and smudge the printed sheet. A projection 82 prevents this by standing over the shoulder 83 of the adjusting-blade 242 of the mold when the matrix-carrier registers with the latter and holds the latter down upon the front edge 85 of the bottom 220 of the said mold, thereby providing for the casting of a space lower to paper than one cast against a matrix 68 without a formative cavity 69, such as the bottom one of the three shown in Fig. 15, by the width of the nose of the blade 242. 86 is an inverted cup having locking-rings of radial holes 87 of a common diameter 55 in its periphery. There are as many holes in each locking-ring or ring of holes as there are matrices 68 and pairs of projections 81 82 in a tier or font. If there is only one font in the matrix-carrier, there is only one ring of holes. Each hole or column of holes 87 stands vertically alined with its respective matrix 68, column of matrices 68, or pair of projections 81 82. The cup 86 is held fast to the annulus 64 of the matrix-carrier by any suitable means, 65 such as shoulders 88 89 on each, screws 90, and

steady-pins 91. A locking-pin projects to the front from the machine-frame 32 vertically underneath the mold and in a proper position to receive a locking-hole 87 when the respective matrix 68 or pair of projections 81 82 is 70 moving truly up to the mold. The diameter of the front portion 92 of the pin is such that it will receive a hole 87 on it with a working fit. Behind the portion 92 there is a concave shoulder 93, so positioned that the periphery of the 75 cup 86 shall bear against it as soon as the matrix-carrier is in metal-tight contact with the face of the mold, so that unnecessary pressure of the former against the latter is prevented.

94 is a vertical rod about which the matrix-carrier is turned for change of character and up and down which a multiple-font matrix-carrier is moved for change of font. This rod turns in a suitable journal-slide 36, and therefore moves with the latter. The upper 80 part of it is turned down to produce the shoulder 95 and the annulus 64, bored to fit over it with a working fit and rest upon the said shoulder. It is held to the shaft by a slot-and-feather device 96, while the top end of 90 the shaft is tapered, the bore of the annulus being coned to correspond, and finally screw-threaded to receive a holding-down nut 97. This provides for a matrix-carrier being readily taken off the machine and another one 95 equipped with a different series of fonts substituted for it.

199 is a ball-bearing shown in section in Fig. 11 and fixed on the slide 36.

The following emergency locking device is 100 provided: The rod 94 carries a disk 98, which is fast on it and the object of which is described farther on. Its presence is utilized to coöperate with a detent 99, Fig. 11, fixed to the machine-frame 32 by providing its periphery with as many notches 100 as there are matrices in a font. These notches are preferably of the shape shown in Fig. 30. Each time that the matrix-carrier advances to the mold the disk 98 is carried with it, a notch 105 110 100 engaging with the detent 99. Thus a pin 92 coöperates with a hole 87 and a notch 100 with the detent 99 synchronously; but the last-mentioned coöperation is strong enough to lock the matrix-carrier in the event of the 115 pin 92 being broken off.

Turning the matrix-carrier for change of matrix.—The means for doing this are illustrated in Figs. 1, 2, 3, 4, 5, 20, 22, 24, 25, 26, and 28 and are as follows: The controller 24 120 passes from the paying-out drum 26 between an air-chamber 101 in the base of the standards 35 35, already described, and the opposite face of the machine-frame 32. Air under pressure is constantly being fed by any 125 suitable means into the chamber 101 through the pipe 102, which latter is controlled by the cock 103. The bottom of this air-chamber has a row of six ports 104, Figs. 20, 22, and 24, so positioned in it that all the perforations 11 in 130

any transverse row in the controller 24 will find a port 104 to register with. Only the six ports 104 coöperate with the perforations. The remaining five coöperate with the font-changing perforations 17 to 21 and are described farther on. It is essential that the blank portions of the controller should keep the bottom face of the air-chamber 101 closed airtight, and for that purpose an elastic cushion 105 is checked into the above-mentioned opposite face of the main frame 32, as shown in Fig. 22. 106 represents ports through the respective part of the main frame. There are six of them, because there are or may be six horizontal rows of controller perforations 11. Each of these ports 106 delivers the air that passes into it through a perforation 11 into one of a series of six cylinders 107, Figs. 20 and 22, through a pipe 108, all the latter entering the respective cylinders at the same end. To facilitate their connection to the machine-frame 32, the top ends of the six pipes 108 are made fast to a plate 122, Figs. 22 and 27, perforated to register with the ports 106 and held to the said frame. The series of cylinders is shown as formed in a block 109, fast to the machine-frame 32. Each cylinder is fitted with a free piston 110, to which is made fast a push-rod 111, the outer end of which bears against the rear face of the top end of a respective lever 112, fulcrumed on a shaft 113, held suspended from the machine-frame 32 by a pair of hangers 114 114, Figs. 4 and 20. 115 115, &c., are six similar horizontal slides standing one upon the other between two rails 116 116, fixed by their ends to the machine-frame. There is a ball-race 117 between each slide 115 and its adjoining slide 115 or rail 116, as the case may be, to facilitate their sliding movement past each and the rails 116 116. Each slide 115 is held to the machine-frame 32 by the means illustrated in Fig. 25. There is a slot 118 in the rear side at each end extending from the latter for a distance not less than the motion of a slide in either direction, there being a similar slot 119 in the front, as shown in Fig. 4. A screw 120 is passed through each pair of slots 118 119 and an antifriction-roller 121 in the slot 118 into the machine-frame. The swing of the bottom end of a lever 112 to the left moves the respective slide 115 through an arm 123, fast to the respective slide and holding its rear end in contact with the bottom end of its actuating-lever 112. There is a suitable device—such as a spring 136, Figs. 6 and 9—to return each slide 115 to the right and its lever 112 to its original position, both as soon as such slide is ready to be returned. 124 represents holes, and 125 represents stops distributed at equal distances from each other and in vertical columns over the front faces of the six slides 115. The left-hand column consists of holes 219 only and is part of a safety device. The number remaining (fifty) corresponds with the number

of columns of matrices in the multiple matrix-carrier. The holes 124 of the fifty columns are so arranged on the respective slides 115 that when the air-blasts through one transverse row of perforations 11 in the controller 24 has moved the corresponding slides 115 to the left there shall be somewhere along the series of slides a column of holes 124 corresponding in point of relative position with the perforations 11 in the said transverse row. Coöperating with the fifty columns of holes 124 and stops 125 are fifty upright arms 126, pivoted by their bottom ends upon a shaft 127, Figs. 4 and 20, supported by its ends in the machine-frame 32. These fifty arms (together with the one that coöperates with the above-mentioned left-hand column of holes 219) are prevented from moving laterally on their shaft by some suitable means, such as by projections 144 144, and stand opposite the spaces between the columns of holes 124 and stops 125 before any of the slides 115 are moved to the left, as shown in Figs. 4 and 5. Each arm 126 is urged toward the series of slides by a spring 128, pulling on it from a fixed point behind it on the machine-frame, and has a horizontal shoulder 129 on its rear edge and has a rearwardly-projecting stud or studs 130 to engage in all the holes 124 standing opposite to it after the motion of the selected slides 115 to the left has been effected. 131 is a cylinder whose shaft 132 is turned in bearings 133 133 by a belt 134, passed round the pulley 135, fast on the main shaft 62, and a pulley 137, loose on the shaft 132. The right-hand face of the pulley 137 has a leather face 138 to facilitate working contact between the said pulley and a disk 139, held to the shaft 132 by a feather-and-slot device 140 and urged up to the leather face 138 by a spring 141, the strength of which is under the control of a screw-threaded nut 142 on the respective end of the shaft 132. 143 143 are fifty equal projections arranged in a spiral line on the periphery of the cylinder 131, Figs. 4 and 20, each projection being exactly opposite one of the arms 126 to coöperate as a stop with the respective shoulder 129 and corresponds with a transverse row of perforations 11 in the controller 24, as well as with the adjusted column of holes 124 in the slides 115, which corresponds with the said transverse row.

The left-hand end of the cylinder-shaft 132 projects past the cylinder 131 and carries the miter-wheel 145, fast on it. The latter gears with a second miter-gear 146, fast on the bottom end of a vertical sleeve 148, Figs. 4 and 69, through which passes a coaxial rod or shaft 147, which is held to the said sleeve, but only so as to be rotated by it by a feather-and-slot device 149. This sleeve is capable of turning in a bearing 150, fast to the machine-frame 32. The top end of the rod 147 is connected by a gimbal-joint 151 to a connecting-rod 152, the

opposite end of which is connected by a gimbal-joint 153 and a fork 154 to the bottom end of the rod 94, which supports the matrix-carrier and its locking-ring cup 86. Both gimbal-joints 5 151 and 153 stand in the same position with reference to the axis of the connecting-rod—*i.e.*, with one axis at right angles with the direction in which the slide 36 reciprocates before the matrix-carrier is turned, Figs. 4 and 11—10 to allow of the said rod following the motion of the said slide. As soon as the slides 115 are adjusted by the respective pistons 110 and levers 112 to present a column of holes 124, corresponding with the transverse row of perforations 11 then in the air-chamber 101, the 15 stud or studs on the corresponding arm 126 are pulled by the respective spring 128 into the respective holes. This has the effect of presenting the shoulder 129 on the said arm 20 126 in the path of the respective projection 143 on the cylinder 131, which is at the time being turned by the belt 134 in the direction indicated by the arrows in Figs. 20 and 69, and therefore turning the matrix-carrier 63 25 about its axis. When the latter has been turned far enough to bring the selected matrix opposite the mold, the respective projection 143 on the cylinder 131 engages with the shoulder 129 on the respective arm 126, where-30 by the said cylinder is stopped, and the matrix-carrier with it.

It might happen that the above-mentioned adjustment of the slides 115 would present a combination of holes 124 to some one arm 126 35 other than the one corresponding with the transverse row of perforations 11 then in the air-chamber 101, in which case the respective spring 128 would pull that one arm into engagement with the slides 115, and so cause the 40 matrix-carrier to stop with the wrong matrix opposite to the mold. To prevent such an accident is the function of the stops 125, and those in the column opposite to the said arm 126 would prevent the stud or studs 130 entering 45 the respective hole or holes 124 in the slides 115 opposite to the said arm.

The cylinder 131 is freed from any shoulder 129 by rocking the respective arm 126 to the front. This is accomplished by means illustrated in Figs. 6, 7, 9, and 20. 155, Figs. 6 and 9, is a spring pulling from a fixed point on the machine-frame upon an arm 156, fast on the rod 157, Figs. 6 and 7, and which carries a series of half-cranks 158, the outer end 55 of one of which is connected by a link 159 to the bottom end of the lever 61, already referred to. The crank-pin 160 of each half-crank 158, Figs. 6, 7, 20, and 26, works in a slot 161 in a connecting-rod 162, the front 60 ends of the series of rods 162 being pivoted to a bar 163, working through the bottom rail 116. The spring 155 keeps the top end of the lever 61 in touch with the finger 38 on the slide 36, Fig. 8, and both of which 65 parts have been already described. When

the slide 36 is moved forward to make the matrix-carrier press the selected matrix up to the mold, the crank-pins 160 slide along the slots 161, Fig. 26, from the rear to the front ends thereof, and having then come up to the 70 connecting-rods 162 and the slide 36 continuing to move they push the bar 163 to the front, thereby freeing the cylinder 131 from the control of the arm 126 in question and also disengage the latter from the respective 75 slides 115. The lost motion between the crank-pins 160 and the connecting-rods due to the slots 161 gives the particular hole 87 in the locking-ring of the matrix-carrier time to engage with the locking-pin 92. The bar 80 163 is moved back again by a series of springs 207, depending from the rear side of the top rail 116. The next adjustment of the slides 115 begins as soon as the bar 163 has rocked the arm 126 clear of the cylinder 131 and the 85 slides 115, and on its conclusion the slide 36 is retracted to the front, taking the matrix-carrier with it.

Raising or lowering the matrix-carrier to change font.—The means for effecting this 90 are seen best in Figs. 4, 19, 20, 24, 27, 29, 30, and 31. The five ports 164, Fig. 24, in the bottom of the air-chamber 101—three of them on the right and two on the left of the six ports 104, already described—correspond with 95 the five font-changing perforations 17 to 21 in the controller, Figs. 1 and 3. There is a port 165 through the adjacent part of the machine-frame 32 opposite each port 164. A tube 166 leads from each port 165 to a cylinder 167, Figs. 4 and 29, having a piston 168 and a push-rod 169. All these push-rods are at varying distances from the front, the one nearest to the front coöperating with the bottom font and the one farthest from the front 100 with the top font but one. The coöperation of the controller with the ports 164 165 is the same as described with reference to the ports 104 106 and the coöperation of the five pistons 168 and their push-rods 169 with the five 110 perforations 17 to 21 the same as described with reference to the six cylinders 107, six push-rods 111, and transverse rows of controller-perforations 11. Each piston 168 is fitted with a returning-spring 175. The five cylinders 167 are all bored in a cylinder-block 170, supported under the adjacent portion of the machine-frame 32, Fig. 29, by studs 171 172 entered into lugs 173 174, depending from the 115 said portion of the frame. The lugs 173 174 120 are separated by a distance greater than the width from front to rear of the cylinder-block 170 to make room for a reciprocating motion of the latter from front to rear and the object of which is described farther on. 176 is 125 a spring resilient between the rear lug 173 and the rear or opposite side of the cylinder-block 170 to urge the latter toward the front of the machine. 177 is a bell-crank lever fulcrummed at 178, actuated by a spring 179, re- 130

silient between the front side of the cylinder-block 170 and the front arm of the lever 177, standing up between it and the lug 174. The longer and horizontal arm of the lever 177 extends to the rear and has an upturned nose 180, adapted by being swung up in front of the lug 173 to lock the cylinder-block 170 in its then position. The reciprocating slide, Figs. 8, 19, and 69, 36 has already been mentioned. It is actuated, Fig. 11, by the upstanding arm of a bell-crank lever 181, fulcrumed at 182 in the machine-frame 32, the other arm engaging in a cam-groove 183 in a cam 184, fast on the main shaft 62. To facilitate the motion of the slide 36, it is carried on ball-bearings 185, confined between a pair of stops 186 186. 187, Figs. 19 and 20, is a push-piece carried by a bracket 188, projecting laterally from the slide 36 and projecting from it to the rear to disengage the nose or stop 180 from before the lug 173 by pushing on the nose 189 of the upstanding arm of the bell-crank lever 177. The distance that the push-piece 187 projects to the rear of the lug 188 is adjustable by its being carried in a chamber 190 therein and screwed onto a screw-threaded rod 191, turning in the bracket 188 and prevented from moving to the front by a collar 192, bearing against the bottom of the chamber 190. The rod 191 is continued through the bracket 188 to the front thereof, where it carries a square 193 or its equivalent for turning it, also a lock-nut 194. 195, Figs. 19 and 31, is a bell-crank lever fast on a shaft 196, turning in bearings depending from the slide 36. The operative nose 197 of the upright arm of the lever 195 stands to the front of and opposite to any of the push-rods 169 when the latter are protruded beyond the left side of the cylinder-block 170. The horizontal arm of the said lever 195 extends to the front under the disk 98, with which it maintains constant contact. As the nose of this last-mentioned arm is the immediate raising agent, and as the disk 98 may be turning about its vertical axis while it is being raised or lowered, it is fitted with antifriction-balls 198. The means above described act as follows: Assuming that the controller 24 presents one of the font-changing perforations 17, 18, 19, or 21 to a pair of opposite ports 164 165, a blast of air along the respective tube 166 will protrude the respective push-rod 169, which will then stand in the forward path of the operative nose 197 of the bell-crank lever 195, Fig. 19. The rearward movement of the plate 36 carries the lever 195 likewise to the rear (that is, as it is moving the matrix-carrier toward the mold) until the nose 197 of the upstanding arm of the lever 195 is stopped by the protruded push-rod 169. (The lever 195 would be rocked just the same by the rearward motion of the slide 36 if there were no perforation 17, 18, 19, 20, or 21 in the air-chamber 101 at the time, but without effect.)

The slide 36 continuing its motion to the rear, the nose 197 is rocked to the front, (assuming that the desired change of font involves a raising of the matrix-carrier,) and thereby making the horizontal arm raise the matrix-carrier accordingly by engaging with the disk 98. If the change of font involves a lowering of the matrix-carrier, a push-rod farther from the front is protruded, and during the time that the nose 197 is moving up to it the weight of the matrix-carrier and attached parts lowers the former until the horizontal arm of the lever 195 stops it. Obviously the raising or lowering of the matrix-carrier must be completed before a hole 87 in any one of its locking-rings engages on the pin 92, and it is also synchronous with the already-described motion of the matrix-carrier about its axis for change of matrix. For this reason the protruded push-rod 169 must be prevented continuing to rock the bell-crank lever 195. To this end the duly-adjusted push-piece 187 then being carried to the rear by the slide 36 engages the nose 189 and disengages the nose 180 from the lug 173, thereby allowing the cylinder-block 170 to move to the rear against the resilience of the spring 176, the angular position of the bell-crank lever 195 remaining unaltered, because the said block 170 continues to move until the slide 36 has completed its movement to the rear. The adjustment of the matrix-carrier for change of font is completed just before the disengagement of the nose 189. The matrix-carrier and the slide 36, together with their attached parts, are returned to their original and normal position near the front of the machine by the forward rock of the upstanding arm-lever 181.

The somewhat considerable weight of the matrix-carrier and its attached parts requires to be counterpoised. This is done, Figs. 4, 7, and 11, by a weight 200, adjustable on a lever 201, fulcrumed at 202 on the machine-frame 32 and having its front end forked to receive the two pins 203, which project laterally from opposite sides of a collar 204, connected to the bottom end of the rod 147 in such a way that the latter can turn freely in it.

It is possible that the antifriction-rollers 198, Fig. 19, in contact with the disk 98 may be worn down to a smaller size. This would prevent the proper rock of the bell-crank lever 195 raising the matrix-carrier high enough and also allow of it to drop too far. Either error would result in the pin 92 and the locking-holes 87 being worn. To obviate these inaccuracies, the rearward projection 205 of the slide 36 is fitted with a set-screw 206, working vertically therein and so positioned therein as to bear against the under side of the horizontal member of the lever 195 to take up the wear of the rollers 198.

Provision for accidents to the controller while it is in the air-chamber.—If the control-

ler 24 should from any cause present an unperforated portion to the two series of air-ports in the air-chamber 101, the matrix-carrier is turned about its axis to present a vertical plate 8 to the mold (whereby a space will be cast) by the following means. Referring to Figs. 4, 11, and 43, each of the slides 115, Fig. 4, carries a prolongation 208, which lies in a transverse member of the machine-frame 32, and with its left end flush with the left side thereof, so long as the respective slide remains over to the right. A plate 209, Figs. 4 and 11, is pivoted near its rear and vertical edge in a pair of sockets 210 210, fixed to the outside of the said transverse member and so positioned thereon that when the plate 209 is swung to the said member the front portion of it shall be in touch with all the prolongations 208. 211 is a finger fast to and depending from the plate 209 at a point between its front edge and its axis and entering an eye 212, Figs. 11 and 43, fast to a lever 213, fulcrumed to the front of the machine-frame at 214. The rear end of this lever is held by a spring 215, pulling from a fixed point on the machine-frame, on a finger 216, projecting from it normally in the path of a projection 217 on the cylinder 131. This projection occupies a position about the periphery of the cylinder 131 corresponding with a vertical plate 8, being opposite to the mold. The action is as follows: So long as the roller 24 presents each time it pauses in the air-chamber 101 one or more character-perforations to the coöperating air-ports a corresponding number of slides 115 is moved to the left, the plate 209 is swung to the left, and the nose of the lever 213 is rocked to the left out of the path of the projection 217; but if the controller should present an unperforated portion none of the slides 115 are moved, and the cylinder 131 is stopped by the projection 217.

If the controller 24 should be torn or broken, as soon as the portion so damaged gets into the air-chamber the fifty-first arm 126, (being the one on the extreme left,) and which has six studs 130, will engage in the left-hand column of holes 219 in the slides 115, and thereby stop the cylinder 131 in the same way as one of the arms 126 would have stopped it if the controller had presented a row of perforations 11.

The mold.—This organ of the machine is shown as a whole in Figs. 4, 7, 8, and 69, in which it is marked with the reference A. The details of it are shown in Figs. 4, 7, 8, 11, 19, 32 to 42, 47, 48, 49, and 51 to 56. The mold is moved from the casting position to the trimming position, from the latter to the ejecting position, and back again to the casting position upon the hard-faced top 220 of an up-standing portion of the machine-frame 32, Figs. 4, 7, 11, 19, and 54, by a lever 221, Fig. 7, fulcrumed on the back of the machine-frame 32 at 222 and rocked by the engagement of its lower end in the cam-groove 223 in the

cam-body 184, Figs. 4, 7, and 69, fast on the main shaft 62. There is a slot 224 in the machine-frame 32 to make room for the top end of the lever 221, which engages with the mold A by standing in a continuation 225 of the said slot. The top or platform 220, above mentioned, provides the bottom face of the mold, and the latter moves, Figs. 4, 8, 11, 20, 47, and 56, between two guides 226 227, the former in front of it and the latter behind it and both fast to the machine-frame 32, a projection 228 on the top edge of the guide 227 engaging in a slot 229, Figs. 8, 33, and 36, in the top plate 230 of the mold. The latter is kept in working contact with the top 220, Figs. 4, 7, and 8, by a roller 231, mounted in the left end of a lever 232 of the first class, fulcrumed at 233 in a post 234, fast to the front guide 226, the roller 231 being pulled forcibly down upon a bar 235, fast lengthwise on the mold top plate 230 by a spring 226 pulling the end of the lever 232 opposite to the one that carries the roller 231 upward from the overhanging end of a pillar 237, to which it is made fast. The bar 235, Figs. 4, 7, 8, 35, 36, and 37, provides a path for the roller 231 and is inclined upward to strengthen the contact between the mold and the top 220 when the former is in the casting position. The mold A consists of five principal pieces, the two blocks 238 239, the top plate 230, already mentioned, the latter fast upon the top of the two former, and the block 239 adjustable to and from the block 238, Fig. 35, and the two slides 241 242, Figs. 11, 35, and 47, and which together form the top of the mold-cavity 240, Figs. 38 and 40. Fig. 68 shows the position of a type in the mold-cavity, the face *a* being the back of the type-body, the opposite face *b* the belly, *c c* the two sides, *d e* the two side bearings or distances from the type-face *f* to the respective side *g*, *g* the setway dimension, and *h* the height.

The improved mold possesses the following capacities for being automatically adjusted for certain dimensions of the types and spaces.

1. *Adjustment for setway dimension of each type-body in a font according to the same dimension of the respective type-face.*—The means for effecting this adjustment are shown best in Figs. 32, 41, and 47. The principal slide 241 and the secondary slide 242 are of the same thickness. The former stands behind the latter, both edge on to the front between the two blocks 238 239 and between which they are capable of reciprocating in a vertical direction with a metal-tight working fit. When they are at rest, their feet stand down upon the platform 220. The respective tops of these two slides terminate in rods 243 244, sliding through a guide 245, Figs. 4, 7, 11, 35, 37, and 47, supported by the top plate 230. Both slides are connected together and are at the same time capable of independent motion, as follows: 246 is a collar or a sleeve

fast on the rod 243, the said collar resting upon the top of the slide 241. 247 is a shoulder on the slide 242, and on it rests a collar 248, loose on the said rod and incorporated with a second collar 249, resting upon the collar 246. 250 is a piece fast to the collar 246 and fitting close to the rear side of the collar 248. 251 is a spring resilient between the guide 245 and the collar 249, and therefore constantly urging the slide 241 down upon the platform 220. 252 is a lighter spring resilient between the collar 248 and a collar 253^a, fast on the rod 244 near to but below the guide 245. Thus raising the slide 241 compresses the spring 251 and raises the slide 242; but the latter may be held down upon the platform 220 and the slide 241 still be raised, because the spring 252 would yield before the rising collar 248. The shoulder 247 is so positioned on the slide 242 that when it is bearing against the collar 248 the bottom edges of both slides 241 and 242 are flush with each other. The reader will remember in connection with Fig. 15 that there coöperates with each matrix-body 68 a projection 78 and that this projection is longer or shorter than that which coöperates with any other matrix for a type having a different setway dimension. As a matrix is about to register with the mold A its projection 78 engages, Figs. 35 and 41, the nose 253 of a bell-crank lever 254, fulcrumed on a rod 255. The nose 253 is held normally projecting to the front of the mold A by a spring 256. 257 is a lever, Fig. 41, of the third class, having its fulcrum 258 to the rear in a bracket-piece 259, fixed to the plate 230 of the mold. 260 is a pin standing upon the bell-crank lever 254 and having the lever 257 resting upon it. These parts are so arranged that when they are in the position just described the two slides 241 242 are down on the platform 220, the piece 250 (which is long enough for the purpose) resting upon the lever 257 between the pin 260 and the front end of the said lever. The piece 250 is the one by which both the slides 241 242, or only the former, are raised to make the mold-cavity. Thus the longest projection 78, coöperating with the matrix having the longest setway dimension, will raise the pair of blades 241 242 higher than a shorter one, each projection 78 making the setway dimension of the mold-cavity to exactly meet the requirements of the respective matrix 68 and type to be cast from it. If the fulcrum 258 were fixed, the rise of the lever 257 might be too much or too little for a given font. The present invention adapts the said lever to meet the requirements of any font by fitting the bracket-piece 259 to slide upon or in a suitable guide on the top of the plate 230 and fitting it with an adjusting-screw 261, passing through the bracket-piece 259, in which it has only a motion about its axis, and engaging in a screw-threaded hole 262 in the plate 230, so that the raising effect

of a given lift of the pin 260 upon the piece 250 can be easily modified in either direction by changing the relative lengths of the lever 257 before and behind the pin 260, and this will give a variation of setway dimension accordingly. 70

2. *Adjustment for setway dimension of top side bearing d.*—Type as hitherto made have the type-face f midway between the two sides c e, the two side bearings d e being as a consequence of the same width; but circumstances sometimes arise which make it desirable that a certain font should have the top side bearings d wider than the bottom side bearings e. It is to comply with such circumstances that 80 this second adjustment has been devised. It is effected by moving the fulcrum 258 of the lever 257, Figs. 41 and 47, to front, thereby increasing the raising effect of a given rise of the pin 260 upon the piece 250. The means 85 for adapting the lever 257 to meet the requirements of any font coöperate also with the adjusting means just described. It might appear to the reader that the result of this second adjustment is substantially identical with 90 the result of the first adjustment described in the preceding paragraph; but this is not so, for each formative cavity 69 (see Fig. 15) is so positioned upon the respective block 68 that it will present itself to the mold when the 95 latter is adjusted, as described in the said preceding paragraph, midway between the top 220 (see Fig. 47) and the under sides of the slides 241 242, under which circumstances both side bearings d and e will necessarily be equal 100 to each other; but this second adjustment does not replace the first adjustment, but is additional to it.

3. *Adjustment for casting a given font upon type-bodies of a larger font or to make them self-leading by casting an extension of the type-body upon each.*—This is effected by substituting another pair of slides 241 242 for the pair in the mold, because each size of body requires its own pair of slides. 276, Figs. 38, 105 39, 40, and 47, is a dovetail distance-piece 110 capable of vertical motion between the two blocks 238 239 and constantly urged down toward the platform 220 by a spring 277, resilient between the plate 230 and itself. Because it is a distance-piece between the two blocks 238 239 it holds them the proper distance apart for the belly-to-back dimension—*a b* in Fig. 68—of the type-body. 263, Figs. 35, 36, 47, is a T-shaped piece screwed to the 120 front of the plate 230 and coöperating with the latter to keep the two slides 241 242 straight. The plate 230 is held down on the block 238 by the screws 264 and on the block 239 by the screw 265 and has a dovetailed projection 266, Figs. 33 and 34, which engages the dovetailed groove 267, Fig. 65, of the block 239, the two serving as a guide for the motion of the said block to and from the block 238. 255, Fig. 40, is the before-men- 125 130

tioned pin which passes horizontally through the block 239 into the block 238, to which it is held by a screw 269, accessible from the front. 270 is a milled head-sleeve internally 5 screw-threaded to engage with the correspondingly screw-threaded portion of the pin 255 and working in a bore 271 in the block 239 against the resilience of a spring 272 to adjust the said block up to the slides 241 242. 10 To take out the said pair of slides previous to substituting another pair of a different size, unscrew the screw 265 and sleeve 270 and take block 239 and T-piece 263 off the mold A. Take out the two slides 241 242 and the distance-piece 276. Then insert another distance-piece 276 of the proper size to correspond with the substitute pair of slides, insert the latter, and replace the other mentioned parts in the proper order. For the purpose of this 15 adjustment each mold is equipped with a series of distance-pieces and pairs of slides of different dimensions, each distance-piece of the same dimension as the coöperating pair of slides.

25 *4. Adjustment for position of type-face f between back and belly.*—This is effected by the screw-stop 273, Fig. 4, adjustable horizontally to and from the lug 274 on the mold A through the machine-frame 32 and fitted 30 with a lock-nut 275. It is this stop 273 that limits the return motion of the mold A from the left to the right or casting position, and as the type is cast on one of its sides *c*, Fig. 68, it is evident that the more or less the mold 35 is allowed to move to the right before it is stopped the nearer to or farther from either back or belly will the type-face *f* be.

35 *5. Adjustment for spaces of less height to paper than the type-bodies.*—This is effected 40 by means illustrated in Figs. 15 and 47. A projection 81 engages with the nose 253 of the bell-crank lever 254, Figs. 41 and 47, to raise the slide 241 to the proper height in the same way as already described for type with reference to the last-mentioned two figures and at 45 the same time the coöperating projection 82 engages over the shoulder 83 on the slide 242, thereby holding the latter down upon the projection 85, Figs. 47 and 54, from the platform 50 220, so that the space is cast less than the height *h* of a type-body by a distance equal to the width of the said slide 242.

55 *Cooling the mold.*—In view of the fact that the present machine is to work at a high speed, artificial means of cooling it by a suitable fluid, such as either cold air or water, is necessary. The cooling-conduit starts at 278, Fig. 7, in the back of the main frame 32, emerging at 279, Fig. 51, enters the plate 220 at 60 280, Figs. 47 and 55, emerging at 281, Figs. 7, 47, and 55, enters the back mold-guide 227, Fig. 56, at 282, emerging by the pipe 283 to join (by means of a flexible junction-tube, not shown) the pipe 284, Figs. 35 to 38 and 65 65 65, projecting from the block 239, enters the lat-

ter, Fig. 40, at 285, emerges at 286 into the pipe 287, Figs. 36, 37, 38, and 65, and which is connected by a flexible tube (not shown) to the pipe 288, Figs. 35 to 37, screwed into the block 238. From there it is continued to the 70 bottom of the block 238 into the port 289 in the plate 290, fixed on the bottom face of the block 238, through the block 238, Fig. 39, and out through the pipe 291, Figs. 35 and 37.

75 *Casting mechanism.*—This shows best in Figs. 10 to 13. The metal-pot 292 rests upon a casing 293, which latter has a slide 294 capable of a transverse motion in either direction in a guide 295 on the machine-frame 32 under the action of a hand traversing screw 80 296, engaging in a nut 297, depending from the said slide. 298 is the gas-burner. 299 is an inner compartment of the metal-pot, and 300 is a metal-port between the bottoms of the two pots 292 and 299. 301 is the piston, 302 85 its cylinder, and 303 its rod screwed into the piston and working in a guide 304, supported by the pot 292. 332 is a third compartment of the metal-pot next to the burner 298, and therefore hotter than either 292 or 299. 90 305 is a central port extending up the piston 301 from its bottom face, and 306 a lateral port from it to register at the proper moment with the port 300. 307 is a non-return valve of lighter specific gravity than 95 the type-metal and controlling the bottom end of the port 305 when the piston 301 descends. A rise of the piston admits metal into the compartment 332, the rise of the metal therein closing the valve 307, and a descent of 100 it expels a charge of metal up the throat 308 and out through the nozzle 309, over which stands the back portion of the mold-cavity 240, the screw 296 having been previously adjusted to make the rear face of the port 310, 105 Fig. 47, in the back guide 227 fit up to the angular shoulder 311 on the nozzle, as shown in Fig. 11. The following means are provided to insure that the piston 301 shall make its downstroke at the same time that a matrix-body 68 contacts with the mold A: As the slide 36 is being moved toward the latter by the lever 181, already described, it pushes the nose 312 (shown in detail in Figs. 45 and 46) of a lever 313 up an incline 314, held to the machine-frame 32 and vertically adjustable thereon by a set-screw 315, and through a hole in the rear of the machine-frame. This lever 313 is pivoted at 316, Figs. 11 and 19, to an extension of the slide 36, provided for that 110 purpose, and carries on its side a roller 317, adapted to ride up the incline 314. 318 is a spring the tension of which is adjustable by a screw-and-nut device 319, pulling from a bracket 320 on the machine-frame upon the 115 front arm of a bell-crank lever 321, fulcrumed, Fig. 7, in brackets 322 322 on the machine-frame and holding its top end in the path of the nose 312, so that the rearward motion of the said nose will rock the lever 321 back and 120 125 130

stretch the spring 318. 323 is a rearwardly-projecting arm fast to the fulcrum of the lever 321 and connected with the piston 301 by a rod 324, a lever 325, fulcrumed at 326 above the metal-pots, and the piston-rod 303, respectively, connected as shown in Fig. 13. The parts just described are so proportioned and positioned that at the moment when the matrix-body 68 contacts with the mold A, or just before that, the travel of the roller 317 up the incline 314 raises the nose 312 above the top end of the lever 321, thereby leaving the spring 318 free to contract. This spring forthwith, acting through the said lever 321, the arm 323, and the connections above mentioned, puts the piston 301 through its working stroke smartly, whereby a charge of metal from the third compartment 332 is injected into the mold-cavity 240. The return-swing of the lever 321 is cushioned by the contact of a cavity 327, lined with some resilient substance, with the nose of a rearwardly-projecting screw 328, adjustable in the main frame 32 for projection toward the said cavity. The quantity of metal injected by any descent of the piston 301 is obviously proportionate to the length of that descent and can be regulated by either the length of the piston-rod 303, screwed into the piston, or by the projection of the screw 328, or by both. When the lever 321 has been returned by the spring 318, its top end will be below and to the front of the nose 312. To facilitate the passage of the latter over the former and which will take place the next time that the lever 181 moves the slide 36 to the front, both contacting surfaces are convex, as shown in Fig. 46. The nose 312 is kept down in contact with the incline 314 by a spring 329, Figs. 11 and 44. The respective end of the lever 325 engages with the piston-rod 303 by entering a vertical slot 330, and wear at that point is taken up by screw-nuts 331, working above the said lever on a screw-threaded portion of the rod 303.

For the reason that the matrix-carrier is circular in plan, with a series of projections from its periphery, as shown in Fig. 16, there must be an arc-shaped concavity 333, Figs. 19, 39, 40, and 51, in the machine-frame under the mold A and in the blocks 238 239, as well as in the platform 220, as shown in Figs. 54 and 55. From the central or deepest part of the concavity, so far as it affects the blocks 238 239, there are projections 334 335, Figs. 35, 39, and 40. The height of these projections does not exceed that of the shoulder 83 in the front slide 242. (Shown in Fig. 47.) The third projection, 85, Figs. 19 and 54, has been already described. There is also a cavity 336, Fig. 35, in the front of the T-piece 263, into which projections 82 can enter when a matrix in one of the lower fonts 2 to 6 is required to contact with the mold.

Trimming and ejecting a type or space.—

As some of the trimming of a type is done

before and some of it after the ejection of it from the mold, the respective stages of both trimming and ejecting will be described in the order of their occurrence. As soon as the type has been cast, the lever 221, Fig. 7, moves the mold A in the direction of the mouth 337, Figs. 4, 57, 61, and 62, in the top of the galley. The jet of the type cast in the port 310, Fig. 47, is separated from the respective type-body during that motion of the mold by the following means, which are shown best in Figs. 7, 47, 61, and 62: The spring 277, Fig. 47, holds the distance-piece 276 (both already described) down upon the jet to keep it steady. During the above-mentioned motion of the mold A a roller 338, loose on an arm 339, fast to the distance-piece 276 and engaging in the groove 340, Fig. 56, rides up the inclined portion of the latter, thereby lifting the distance-piece 276 off the said jet. This piece 276 rides up and down a rod 341, secured to the plate 230 by a screw 486, Fig. 47, this rod passing vertically through the said distance-piece and remaining stationary during the movement of the distance-piece. The jet is next pressed against the knife 342, Figs. 7 and 62, fixed on the frame 32, and which first bends the jet and then shears it off, the jet falling down a suitable chute into any desired receptacle. 346, Figs. 37 and 38, is a clearance-space in the bottom of the mold A to enable it to clear the said knife. The continued motion of the mold A carries the type past the knife 344, (shown detached in Fig. 53,) likewise fixed to the frame 32, and which trims the bottom side c, Fig. 68, of it, and at the same time past the knife 345, which removes any fin which may have formed on the same side c at the junction of the respective matrix-body 68 with the mold A. The mold stops when its cavity 240 registers with the above-mentioned mouth 337, Figs. 57, 61, and 62. The lug 274, already mentioned and shown in Figs. 4, 35, 36, and 38, prevents the lever 221 moving the mold too far to the left by engaging with a stop 348, projecting into the path of the said projection from the post 234, already described, and in which it is adjustable, this engagement occurring when exact registration between the cavity 240 and the mouth 337, and which is the ejecting position, is attained. In this connection attention may be called to the fact that the two surfaces—bottom face of the mold cavity and mouth 337—are in immediately contiguous planes, because the mold A has no solid bottom to carry with it. As soon as this registration is effected the type or space, as the case may be, is driven down into the arc-shaped portion 348, Figs. 4, 57, and 61, of the type-race by a pile-driving action of the slides 241 242 imparted to them by the spring 251, Fig. 47, specially compressed for the purpose. Referring to Figs. 4, 47, 48, 49, 349 is a lateral projection from the top of the rod 243 and practically fast to it, save for a

provision against accident duly described farther on. As the mold A is moving to the ejecting position the projection 349 rides up an inclined and forwardly-projecting ledge 350, parallel with the motion of the said mold and carried by a block 356, pivoted at 355 to the top of the fixed arm 351, thereby effecting the special compression above referred to. 5 The projection 349 passes the highest point of the incline 350 at the moment the mold A has attained the ejecting position, 10 whereupon both slides 241-242 are driven down by the expanding spring 251 upon the type or space, pushing it fairly into the mouth 337 until the top side *c* of it is level with the gallery-top. The slides 241-242 are prevented 15 from moving below the said level by the engagement of a stop-screw 353, Fig. 41, adjustable vertically in the lever 257 and engaging with the plate 230, and the engagement of their alined shoulders 354, Fig. 47, with the 20 rod 255, Figs. 41 and 47. The slides 241-242 having ejected the type, the return of the mold A to the casting position begins. The projection 349 should pass under the ledge 350; but it may accidentally—*e.g.*, if the back slide 25 241 has not dropped down onto the rod 255—engage with the end 357 of the ledge and twist the rod 243. To prevent the accident, (previously referred to,) the projection 349 is carried by a collar 358, adapted to turn about the 30 top of the rod 243 through about a quarter of a circle under the control of a pin 359, projecting from the said rod into a slot 360 in the said collar, and a returning-spring 361, so that if the projection 349 does engage with the end 357 the latter turns it to the front far enough to clear the said end. As the projection passes under the incline 350 the latter is raised by it, and after the said projection has cleared the incline the latter is returned to its normal position by a spring 362, pulling from the arm 351 upon a rod fast to the block 356.

Galley and completion of the trimming.—Only one part of the galley has hitherto been described—viz., the type-race 348 and its mouth 337, Fig. 61. The portion 348 is quadrant-shaped in elevation, while the mouth 337 is vertical for a distance equal to the setway dimension of the type. The type pushed into the mouth 337 is pushed through the portion 348 by a vibrating pusher 364, carried by a plate 365, fast on the shaft 366 of a spur-wheel 367, turned by a rack 368, Figs. 4 and 42, pivoted in the hole 369, Fig. 37, in the back of the mold A, which has a taper clearance 370 to receive the rack and to allow of the slight rocking motion caused by the motion of its axis to and from the wheel 367. 5 The rack 368, Figs. 61, are a pair of spring-stops to prevent a type reentering the race. When 65 the mold A begins to move from the casting

to the ejecting position, the pusher 364 is down near the bottom of the quadrant portion 348 up against the last type which it had pushed down before it. The said motion of the mold returns the pusher into the position 70 illustrated in Figs. 61 and 62, ready to act upon the next type ejected into the mouth 337. The type pass from the portion 348 of the race onto the main and horizontal portion 372. The shaft 366 has its bearings in a transverse piece 373, which forms the top of the galley considered as a whole and to which it is held by screws 374, passed through oval instead of round holes to allow of the said top being adjusted to and from the opposite side 75 of the mouth 337 and quadrant portion 348 of the race, as may be required by variations in the back-to-belly dimensions of the font. 80 The knife 375 is a knife fast on the transverse piece 373 to dress the foot of a type after the separation of the jet from it, and 376 is another knife similarly mounted to remove any fin that may have formed on the back *a* at the junction of a matrix-body 68 and the mold A. The knife 377 will remove any fin that may 85 have formed on the belly *b* at the junction of a matrix-body 68 and the mold. Fig. 63 shows how the knives 345 (described in the preceding section) and the knife 377 are mounted on a detachable block 378, screwed to the machine-frame 32. As the type are 90 pushed past the spring-detents 371-371 into the horizontal portion 372 of the race they rest upon a line-support 379, Figs. 50, 57, 61, meeting a resistant 380, carried by a slide 100 381, sliding upon the said line-support and the galley. The line-support 379 is held in its normal position under the assembled line of type by springs 382, Fig. 50, fixed to the back of the galley and entering holes or a slot 383 in the 105 rearward continuation 384 of the line-support 379, and is retracted on the completion of a line to allow it to drop onto the column-support described farther on or onto the preceding line then on that support by the following means: 110 The passage of the last type of the line past the two detents 371 makes the resistant 380 engage the depending nose of the arm 385, fast on the shaft 386, turning in bearings carried by an upstanding arm 387, Figs. 4, 7, and 12, held to the galley-abutment 427 (described farther on) and capable of lateral adjustment thereon by a screw and wing-nut 388. 389 is an arm fast on the opposite end of the shaft 386 and terminating in a fork 390, engaging with the 115 clutch 391, Figs. 8 and 60, sliding freely on a shaft 392, turning in suitable bearings 393-393 on the back of the galley, Figs. 7, 8, and 60. This shaft 392 is rotated, Figs. 6, 7, 12, and 69, from a pulley 417 on the main shaft 62 120 by a crossed belt 394, passing round a pulley 395 on the shaft 396, turning in bearings on the main frame 32, a pair of miter-pinions 397, a vertical shaft 398, turning in bearings 125 on the back of the galley, a second pair of 130

miter-gears 399, a horizontal shaft 400, carrying a spur-pinion 401, that gears with a second spur-pinion 402 on the shaft 392. The rock of the arm 389 engages the clutch 391 with the pinion, Fig. 60, and starts the shaft 392. This latter carries a pair of collars 403 404, adjustable lengthwise of it, each of which has a pair of teeth 405 to engage a corresponding pair 406 on the continuation 384 of the line-support 379. Fig. 50 shows them as about to engage. The motion of the shaft 392 therefore retracts the line-support 379, and the assembled line will be forthwith forced down by the depressor 407, which is depressed against the supporting action of its returning-springs 408, resting in cups 409, standing on the screws 374, by the downward motion of the front end of the lever 410. This downward motion is the result of the engagement of the cam 411 on the collar 404 with the T-shaped rear end 416 of the said lever 410, and which engagement takes place before the teeth 405 have released the line-support 379. As soon as they do release it is returned to the front by the springs 382. As soon as the assembled line has cleared the resistant 380 the latter is returned smartly to its original position against the spring-detent 371 by a weight 412, Fig. 4, hanging from a line 451, fast to the outer end of the resistant-slide 381, and passed over pulleys, so as to make the weight 412 return the said resistant, whereupon the resistance of the spring 413, Fig. 61, (put into tension by the engagement of the stud 424 on the arm 385 with the lever 414, fulcrumed at 415 at the time that the resistant 380 rocked the said arm 385,) acting through the said stud 424 and the connected parts, opens the clutch 391, thereby stopping the shaft 392 before the teeth 405 again engage the line-support 379, which therefore remains in the position shown in Fig. 50. As the line-support 379 is on a level with the bottom spring-detent 371 when that is pushed down by a type, and the depressor 407 is raised by its returning-springs 408 until the bottom of the slots in which they and their cups 409 work bear against the respective screws 374, a partially-assembled line of type of less height from back *a* to belly *b* than the height of the horizontal portion of the type-race would probably "pie" therein for lack of support on its top. To prevent such "pieing," the depressor 407 is fitted with a shoe 425 capable of supplying the necessary support. It is illustrated in Figs. 50, 57, and 58. 425 is the shoe which is held to the depressor and guided thereon by studs 426 projecting from it and engaging in vertical slots 427, and held from the said bottom in a vertical direction by interposed cushioning-springs 428. These springs are strong enough to supply the required support to the smallest type, but will readily yield to the elevating influence upon the shoe 425 of a larger type, especially as

the entrance of the latter under the said shoe is assured by the convexities 429 429 on that end of the shoe which they meet immediately after they have passed the detents 371 371. Nevertheless the shoe 425 must never reach 70 the line-support 379, but must always be out of the way of the returning resistant 380 and its slide 381. To prevent contact between them, both resistant and slide have a central slot 430 through the former backward along 75 the latter, Fig. 59. The pull of the weight 412 on the resistant-slide 381 being constant tends normally to push the last type of the line being assembled against one or both of the detents 371 and to 80 thereby wear down the sharp angles of the type-body. To prevent such pushing, there is applied to the resistant-slide 381 an automatic brake consisting, Figs. 61 and 64, of a lever 418, fulcrumed at 419 on a bracket 420, 85 fast on the galley and having a sharp end 421 meeting the returning slide 381 and held in contact therewith by a spring 422, resilient between the galley and the opposite end 423. The front face of this end 423 is beveled from 90 near the fulcrum 419 in the direction of the rear face of the said end, as shown clearly in Fig. 64, and this front face is normally in contact with the rear face of the lever 414 and which is beveled to the same angle, so that 95 when the lever 414 is rocked to the left the sharp end or operative nose 421 of the brake is rocked away from the slide 381, and while the latter is being pulled to the right the top arm of the lever 414 is rocked to the right by 100 the spring 413.

431 is the galley proper, Figs. 4 and 12, fixed to the machine-frame 32. The top portion of it is vertical, the galley below that being carried to the front from that level till 105 the bottom of it is suitably shaped to provide for the edge 432 of it to register with and deliver the lines of type onto any horizontal surface presented to it to receive them.

433, Figs. 4, 12, and 61, is an abutment extending from the top of the galley to the bottom, and as its function is to adjust the practicable width thereof for length of line it is attached to that side of the galley opposite to the one from which the type are brought, 110 Fig. 4. From that side it is adjustable toward the right side 437 along double V-slides 434 434 and is provided with suitable set-screws and bolts, such as 435 and 479, Fig. 7, to hold it in its adjusted position; but as the 115 upstanding arm 387, Figs. 4, 7, and 12, is fixed to this abutment 433 the fork 390 will be moved laterally also. Consequently both the shafts 392 and 400, Figs. 7 and 60, are slotted to allow of the adjustment therealong 120 respectively of the clutch 391, its co-operating part 438, fast to the pinion 402, the two collars 403 404, and the pinion 401. The pinion 402 is rotated continuously, must sometimes turn with the shaft 392 and sometimes be free 130

of it, and also be capable of longitudinal adjustment with reference thereto. To meet these requirements, the shaft 392 is held against lateral motion in its bearings by a set-screw 439, screwed through the right bearing 393 into an annular groove 440 in the shaft end. The opposite or left bearing 393 receives a sleeve 441, which is long enough to receive the respective end of the shaft 392 and to thereby serve as its left bearing, in fact. It is this sleeve 441 that receives the pinion 402 and its part clutch 438, the two being loosely held to it by a set-screw 442, engaging in an annular groove 443 in the said sleeve. The latter can be moved along the shaft 392 to adjust the position of the pinion 402 and clutch 438 and is fitted with a suitable device for holding it in its adjusted position. To keep the line-support 379, Fig. 50, within the control of the teeth 405 on the collars 403 404, the teeth 406 on the continuation 384 of the said support may be prolonged into ridges, or the continuation 384 may be separate from the line-support, being connected thereto, and therefore adjustable in any position therewith; by a double **V**-groove joint and set-screw. 445 is a slot in the top of the abutment 433 to make room at that end of a short line of type for the descending depressor 407.

The retraction of the line-support 379 from under the first line of type to be assembled allows the latter to drop upon a column-support 446 as long as the width of the galley 431 between the adjusted abutment 433 and the galley side 437. A support 446 may be telescopic for changes in length of line of type, or the machine may be equipped with a series of them of different lengths. The column-support 446 is adapted to slide down the galley under the gradually-increasing weight of the column of lines of type upon it, such downward motion being guided by the engagement of a stud 447 448 on the respective end of the support 446 in a groove 449 450 in the opposite faces of the abutment 433 and galley side 437, as well as by that of two rollers 451 452 in the same grooves. These two rollers are carried at the outer ends of slides 453 454 at a lower level than the studs 447 and 448 and are pushed downward and outward through guides 455 on the column-support 446, either by their own weight or by springs. This support is counterpoised by a counterpoise 456, Figs. 7 and 12, adjustable on a lever 457 lengthwise of the latter and which lever is fast to a fulcrum-rod 458, turning in suitable bearings and carrying a toothed quadrant 459, gearing with a spur-pinion 460, fast on a shaft 461, turning in suitable bearings and carrying a roller 462, fast on it. All the parts 456 to 462, inclusive, are behind the galley 431 and co-operate with the column-support 446 by means of a line 463, having one end made fast to the roller 462 and the other one to the column-support, Figs. 4 and 7, and led over the intermediate pulleys 464 465, carried by the arm 466, turning on the bolt 436, already described, and adjustable laterally thereon to be to the rear of the middle of the column-support 446 and also adjustable in respect of its inclination to and from the front by two set-screws 466 467, one on each side of the bolt 436 and both bearing against the back of the galley 431. So long as the column-support 446 is at the top of the galley, which position it occupies whenever there is no line of type upon it, the counterpoise 456 hangs vertically from the fulcrum-rod 458; but as the weight of lines on the column-support increases the counterpoise is rocked backward and upward, so that its effect increases proportionally with the weight on the column-support 446. The galley 431 may be emptied at any time without stopping the machine, provided that the depressor 407 is not then about to act. To facilitate such emptying, the operator detaches the column-support 446 from the galley by grasping the grips 468 469, Figs. 4 and 8, on the slides 453 454, pressing them toward the grip 470, projecting from the column-support, thereby withdrawing the rollers 451 452 from the grooves 449 450, moving the support 446 until its studs 447 448 register with one of the several pairs of notches in the front faces of the said grooves and pulling the support to the front. To prevent the counterpoise 456 carrying the column-support 446 up to the top of the galley 431 with a rush after it has been replaced therein, the shaft 461, Fig. 7, carries a detent-wheel 471, kept locked by a pawl 472, pivoted on the back of the galley 431, and this pawl must be held disengaged from the wheel 471 by the operator while he steadies the rise of the support up the galley with his hand. 473 is a stop to limit the return motion of the counterpoise as the column-support 446 is moving up the galley.

Driving connections.—These are seen best in Fig. 69. 62 is the main shaft. It carries the coned pulley 417, driven from any suitable motor by the belt 474. The cam 184 on it and having the groove 223 in it reciprocates the mold A by the lever 221. The groove 183, Fig. 11, rocks the lever 181 to reciprocate the matrix-carrier 63. The selecting-cylinder 131 is driven by a crossed belt 134, passed round a pulley 135 on the main shaft 62 and a pulley 137 on the cylinder 131, which turns the matrix-carrier 63 about its axis by the miter-gears 145 146. The shaft 396, that transmits motion to the shaft 392, that retracts the line-support 379 and actuates the depressor 407, Fig. 50, is driven by the crossed belt 394, passing round the pulleys 417 and 395. The pulley 417 is coned to vary the speed of the machine according to the size of the font being cast, and the main shaft 62 carries a fly-wheel 475. This pulley is loose

on the shaft 62 and is locked to it by a clutch 476, Figs. 4 and 8, by a stopping and starting lever 477, Figs. 6, 8, and 11. The respective bearings for the main shaft 62 have projections 478, Fig. 28, entering annular grooves in the said shaft to prevent its being displaced in the direction of its axis.

Referring to Fig. 70 and assuming that the machine completes a cycle of its operations in one minute, the following is a description of the different motions indicated by the respective arcs of the figure and of the time of each. The arrow in the figure indicates the direction in which the matrix-carrier rotates.

15	Arc.	Seconds.
20	B-C Mold A at rest.....	30
	D-C Casting-point.....	
	D-E Injection of metal into the mold-cavity.....	5
	E-F Newly-cast type cooling.....	20
	F-G Mold moving to the ejecting position.....	12.5
	G-H Ejection of a type.....	5
	H-I Mold returns to the casting position.....	12.5
	J-K Mold adjusted for set-way dimension of type-body (time varies from one to three seconds.).....	2
25	L-M Mold distance-piece 276 is raised.....	19
	M-N Type-jet sheared off.....	1
	O-G Mold-slides raised by the incline.....	5
	M-P Mold distance-piece remains up.....	20
	P-Q Mold distance-piece drops.....	9
	D Matrix-carrier stops.....	
	D-R Matrix-carrier remains at rest.....	20
	R-F Disengagement of matrix-carrier from locking-stud on mold.....	5
30	S-T Completion of motion of matrix-carrier from the mold.....	20
	T Matrix-carrier starts toward the mold.....	
	T-K Matrix-carrier reaches the mold at the end of.....	20
	I-D Engagement of matrix-carrier with locking-stud on mold.....	5
	F-T If the matrix-carrier has been raised by a change of font-perforation in the controller, it returns to its original position.....	
35	T-I Raising the matrix-carrier.....	
	F-I Matrix-carrier turns about its axis for change of character--time varies from one to thirty seconds.....	
	T-D Pump-piston raised--maximum time.....	20
	I-D Controller moved one step to present the next transverse row of perforations to the air-chamber and the arms 126 are rocked toward the slides 125.....	5
40	D-R The slides 125 reproduce the transverse row of perforations 11.....	20
	R-F An arm 126 engages the respective slide or slides 125.....	20
	F-I One revolution of the cylinder 131--time varies from one to thirty seconds.....	

45 When the machine constructed as above described is to be used as a type-casting machine only and not controlled by the controller, the main shaft 62 and cylinder 131 are disconnected and the matrix-carrier is turned by hand for change of character and raised or lowered for change of font by adjusting the set-screw 206, Fig. 19, accordingly.

I claim—

55 1. The combination in a type casting and composing machine, of a reciprocating slide; a finger projecting laterally therefrom; a bell-crank lever rocked operatively by the said finger; a pawl-carrier operated by the motion of 60 the bell-crank lever; adjustable connection between the respective arm of the bell-crank lever and the pawl-carrier; a controller-feed drum; a ratchet-wheel loose on the shaft of the feed-drum and actuated by the pawl of the 65 pawl-carrier each time that the finger on the

slide rocks the bell-crank lever; a non-return pawl to lock the feed-drum by engaging with the ratchet-wheel; a crown-gear fast on the side of the ratchet-wheel, a miter-gear fast on the adjacent end of the feed-drum; a miter-pinion driven by the crown-gear and driving the miter-gear; and a spring fast to the machine-base and engaging the pawl-carrier to return it as soon as the return motion of the slide has freed the bell-crank lever. 75

2. The combination in a type casting and composing machine, of a circular matrix-carrier; a vertical rod supporting it in a horizontal position; a font of matrices contained in the said carrier; an adjustable mold for the 80 bodies of the type and spaces; a projection coöperating with each matrix to enter and adjust the setway dimension of the mold for each type; projections to shorten the height-to-paper dimension of the mold for spaces; 85 means for turning the matrix-carrier about its vertical axis to bring the selected matrix opposite to the mold; and means for advancing the matrix-carrier up to the mold, holding the said selected matrix in metal-tight contact therewith and retracting it. 90

3. The combination in a type casting and composing machine, of a circular matrix-carrier, a vertical rod supporting it in a horizontal position; a font of matrices contained in the said carrier; an adjustable mold for the 95 bodies of the type and spaces; a projection coöperating with each matrix to enter and adjust the setway dimension of the mold for each type; projections to adjust the setway dimension of the mold for spaces; projections to shorten the height-to-paper dimension of the mold for spaces; means for turning the matrix-carrier about its vertical axis to bring the selected matrix opposite to the mold; and means for advancing the matrix-carrier up to the mold, holding the said selected matrix 100 in metal-tight contact therewith, and retracting it. 105

4. The combination in a type casting and composing machine, of a circular matrix-carrier; a vertical rod supporting it in a horizontal position; a font of matrices contained in the said carrier; an adjustable mold for the bodies of the type and spaces; means for turning the matrix-carrier about its vertical axis to bring the selected matrix opposite to the 115 said mold; means for advancing the matrix-carrier up to the mold, holding the said selected matrix in metal-tight contact with it 120 and a locking device adapted to perfect the register of the selected matrix with the mold. 125

5. The combination in a type casting and composing machine, of a circular matrix-carrier; a vertical rod supporting it in a horizontal position; a font of matrices contained in the said carrier; an adjustable mold for the bodies of the type and spaces; means for turning the matrix-carrier about its vertical axis to bring the selected matrix opposite to the 130

said mold; means for advancing the matrix-carrier up to the mold, holding the selected matrix in metal-tight contact therewith and retracting it; a locking device adapted to perfect the register of the selected matrix with the mold; and an emergency locking device for the same purpose, coöperating with the said locking device so long as the latter is not broken off, and also capable of substituting it.

10. The combination in a type casting and composing machine, of a drum-shaped multiple-font matrix-carrier; fonts of matrices contained tierwise in it; a vertical rod supporting the said carrier; an adjustable mold for the bodies of the type and spaces; a projection coöperating with each matrix to enter and adjust the setway dimension of the mold for each type; projections to shorten the height-to-paper dimension of the mold for spaces; means for turning the matrix-carrier about its vertical axis to bring the selected matrix opposite to the mold; means for raising and lowering the matrix-carrier in the direction of its axis for change of font; and means for advancing the matrix-carrier up to the mold, holding the selected matrix in metal-tight contact therewith and retracting it.

7. The combination in a type casting and composing machine, of a drum-shaped multiple-font matrix-carrier; fonts of matrices contained tierwise in it; a vertical rod supporting the said carrier; an adjustable mold for the bodies of the type and spaces; a projection coöperating with each matrix to enter and adjust the setway dimension of the mold for each type; projections to adjust the setway dimension of the mold for spaces; projections to shorten the height-to-paper dimension of the mold for spaces; means for turning the matrix-carrier about its vertical axis to bring the selected matrix opposite to the mold; means for raising and lowering the matrix-carrier in the direction of its axis for change of font; and means for advancing the matrix-carrier up to the mold, holding the selected matrix in metal-tight contact therewith and retracting it.

8. The combination in a type casting and composing machine, of a drum-shaped multiple-font matrix-carrier; fonts of matrices contained tierwise therein; a vertical rod supporting the said carrier; an adjustable mold for the bodies of the type and the spaces; means for turning the matrix-carrier about its vertical axis to bring the selected matrix opposite to the said mold; means for raising and lowering the matrix-carrier in the direction of its axis for change of font; means for advancing the matrix-carrier up to the mold, holding the said selected matrix in metal-tight contact therewith and retracting it; and a locking device adapted to perfect the register of the selected matrix with the mold.

9. The combination in a type casting and composing machine, of a multiple-font ma-

trix-carrier; fonts of matrices contained tierwise therein; a vertical rod supporting the said carrier; an adjustable mold for the bodies of the type and spaces; means for turning the matrix-carrier about its vertical axis to bring the desired matrix opposite to the said mold; means for raising and lowering the matrix-carrier in the direction of its axis for change of font; means for advancing the matrix-carrier up to the mold, holding the selected matrix opposite to the mold, holding the selected matrix in metal-tight contact therewith and retracting it; a locking device adapted to perfect the register of the selected matrix with the mold; and an emergency locking device coöperating with the said locking device so long as the latter is not broken off, and also capable of substituting it.

10. In a type casting and composing machine, the combination of a mold for the bodies of the type and spaces, a multiple-font matrix-carrier presenting its matrices through its periphery and capable of motion about its axis for change of matrix to be cast from, along its axis for change of font and transverse to its axis to and from the mold, and fonts of matrices contained in the said carrier.

11. In a type casting and composing machine, the combination of a mold for the bodies of the types and spaces; a circular multiple-font matrix-carrier presenting its matrices through its periphery and capable of motion about its axis for change of matrix to be cast from, along that axis for change of font and transverse to said axis to and from the mold; fonts of matrices contained in the said carrier; means for turning it about its axis; means for moving it along that axis; and means for advancing it to the mold, holding it in metal-tight contact therewith and retracting it.

12. In a type casting and composing machine, the combination of a mold for the bodies of the types and spaces; a circular multiple-font matrix-carrier presenting its matrices through its periphery and capable of motion about its axis for change of matrix to be cast from, along its axis for change of font and transverse to its axis to and from the mold; fonts of matrices contained in the said matrix-carrier; means for turning it about its axis; means for moving it along that axis; means for advancing it to the mold, holding it in metal-tight contact therewith and retracting it; and a locking device adapted to perfect the register of the selected matrix with the mold.

13. In a type casting and composing machine, the combination of a mold for the bodies of the types and spaces; a circular multiple-font matrix-carrier presenting its matrices through its periphery and capable of motion about its axis for change of matrix to be cast from and along its axis for change of font; fonts of matrices contained in the said matrix-carrier; means for turning it about its axis; means for moving it along that axis; means

for advancing it to the mold, holding it in metal-tight contact therewith and retracting it; a locking device adapted to perfect the register of the selected matrix with the mold; 5 and an emergency locking device coöperating with the said locking device so long as the latter is not broken off, and also capable of substituting it.

14. A multiple-font matrix-carrier for a type casting and composing machine consisting of a U-shaped annulus; a top plate projecting beyond the periphery thereof, a bottom flange; rods having their ends entered into the said plate and flange and upon which 10 columns of independent matrices occupy the space between the said top plate and flange, backing up to the periphery of the annulus and threaded upon the said rods; a projection fast to the periphery of the annulus and co- 15 operating with each matrix to control the set-way dimension of the type cast from the respective matrix; projections fixed to the periphery of the annulus to control the length of spaces; projections fast to the periphery 20 of the annulus to control the setway dimension of the spaces; a mold; and a mold-wall comprising two separate parts against which one side of the type or space is cast and which parts are independently adjustable to and 25 from the opposite mold-wall under the control 30 of the above-named projections.

15. In a type casting and composing machine, the combination with a circular multiple-font matrix-carrier adapted to be turned about its axis for change of matrix and along its axis for change of font of rings of holes or locking-rings corresponding as to number of rings with the number of font and as to holes in a ring with the number of matrices in a 35 font, each hole adapted when brought into operative position to pass over a pin projecting from near the mold in the direction of the said hole; and means for putting the hole corresponding with any matrix in operative position and causing it to engage with the said pin.

16. The combination in a type casting and composing machine, of an air-chamber kept charged with air under pressure; a series of ports therein; a series of ports respectively 50 opposite the said ports; a space between the two series of ports adapted to pass the mechanical controller in air-tight contact with the respective surfaces; a series of cylinders with which they respectively communicate; 55 a series of pistons and push-rods fast thereto; a series of slides having holes, and adjustable by the push-rods of the pistons to reproduce, character by character, the character-perforations in the controller; rocking arms adapted to 60 engage the adjustable slides; matrix-carrier capable of being turned about its axis; a rotating cylinder having projections arranged on its periphery according to each of the positions in which the matrix-carrier is to be stopped; a 65 shoulder on each rocking arm adapted to stop

the said cylinder by standing in the path of the respective projection; and gearing between the said cylinder and matrix-carrier adapted to turn the latter.

17. The combination in a type casting and composing machine, of an air-chamber kept charged with air under pressure; a series of ports therein; a series of ports respectively opposite the said ports; a space between the two series of ports adapted to pass the mechanical controller in air-tight contact with the respective surfaces; a series of cylinders with which they respectively communicate; a series of pistons and push-rods fast thereto; a series of slides having holes, and adjustable by the push-rods of the pistons to reproduce, 70 character by character, the character-perforations in the controller; rocking arms adapted to engage the adjusted slides; matrix-carrier capable of being turned about its axis; a rotating cylinder having projections arranged on its periphery according to each of the positions in which the matrix-carrier is to be stopped; a shoulder on each rocking arm adapted to stop the said cylinder by standing 75 in the path of the respective projection; gearing between the said cylinder and matrix-carrier adapted to turn the latter; and means for releasing the said cylinder from the control of each rocking arm.

18. The combination in a type casting and composing machine, of an air-chamber kept charged with air under pressure; a series of ports therein; a series of air-ports respectively opposite the said ports; a space between the two series of air-ports adapted to pass a mechanical controller in air-tight contact with the two surfaces in which the two series of ports stand; means for traversing the said controller through the said space with a step-by-step motion to alternately hold the ports from the air-chamber closed and place the ports opposite to them in communication with them; cylinders connected with the said ports; pistons working therein and presenting push-rods through the cylinder ends; levers adapted to be rocked by the push-rods; slides having holes and adjustable by the said levers; connections between the said levers and slides; rocking arms adapted to engage the adjustable slides; matrix-carrier capable of being turned about its axis; a rotating cylinder having projections arranged on its periphery according to each of the positions in which the matrix-carrier is to be stopped; a shoulder on each rocking arm adapted to stop the said cylinder by standing in the path of the respective projection; and gearing between the said cylinder and matrix-carrier adapted to turn the latter.

19. The combination in a type casting and composing machine, of an air-chamber kept charged with air under pressure; a series of ports therein; a series of air-ports respectively opposite the said ports; a space between the 110

115

120

125

130

two series of air-ports adapted to pass a mechanical controller in air-tight contact with the two surfaces in which the two series of ports stand; means for traversing the said controller through the said space with a step-by-step motion to alternately hold the ports from the air-chamber closed and place the ports opposite to them in communication with them; cylinders connected with the said ports; pistons working therein and presenting push-rods through the cylinder ends; levers adapted to be rocked by the push-rods; slides having holes and adjustable by the said levers; connections between the said levers and slides; rocking arms adapted to engage the adjustable slides; matrix-carrier capable of being turned about its axis; a rotating cylinder having projections arranged on its periphery according to each of the positions in which the matrix-carrier is to be stopped; a shoulder on each rocking arm adapted to stop the said cylinder by standing in the path of the respective projection; gearing between the said cylinder and matrix-carrier adapted to turn the latter; and means for releasing the said cylinder from the control of each rocking arm.

20. The combination in a type casting and composing machine of a controller-feed acting with a step-by-step motion; air-blasts passing through the character-perforations of the controller; push-rods actuated thereby; a set of slides; means actuated by the said push-rods to make the slides reproduce rows of holes corresponding respectively with the transverse rows of character-perforations in the controller; a rotating cylinder having projections; means for stopping it controlled by the said slides; a matrix-carrier movable about its axis and gearing between the said cylinder and it by which the two must turn or stop together.

21. The combination in a type casting and composing machine, of an air-chamber kept charged with air under pressure; a series of ports controlled by a controller having font-changing perforations adapted to coöperate with the said ports to control the discharge of air-blasts through the said ports and the respectively coöperating font-changing perforations; a multiple-font matrix-carrier capable of being moved in the direction of its axis for change of font and mechanism actuated by the said blasts to move the matrix-carrier for a longer or shorter distance along its axis to effect the desired change of font.

22. The combination in a type casting and composing machine, of an air-chamber kept charged with air under pressure, a series of ports controlled by a controller having font-changing perforations adapted to coöperate with the said ports to control the discharge of air-blasts through the said ports and the respectively coöperating font-changing perforations; a multiple-font matrix-carrier capable of being moved in the direction of its

axis for change of font and mechanism actuated by the said blasts to move the matrix-carrier for a longer or shorter distance along its axis in one direction and to stop its motion in the other direction.

70

23. The combination in a type casting and composing machine, of an air-chamber kept charged with air under pressure; a series of discharge-ports therein; a series of ports respectively opposite the said ports; a space between the two series of ports adapted to pass the controller in air-tight contact with the respective surfaces, the controller having font-changing perforations adapted to coöperate with the said two series of ports; a multiple-font matrix-carrier adjustable for change of font in the direction of its axis; a series of cylinders respectively connected with the ports of the second series mentioned above, and fitted with pistons and push-rods, a push-rod to be protruded beyond the respective cylinder end by an air-blast through the respective ports into the path of the lever next mentioned; a reciprocating slide to which the matrix-carrier is connected; and a bell-crank lever carried by the said slide and engaging with the protruded push-rod to engage the matrix-carrier and move it along its axis for change of font.

80

24. The combination in a type casting and composing machine, of an air-chamber kept charged with air under pressure; a series of discharge-ports therein; a series of ports respectively opposite the said ports; a space between the two series of ports adapted to pass the controller in air-tight contact with the respective surfaces, the controller having font-changing perforations adapted to coöperate with the said two series of ports; a multiple-font matrix-carrier adjustable for change of font in the direction of its axis; a series of cylinders respectively connected with the ports of the second-mentioned series of ports and fitted with pistons and push-rods, a push-rod to be protruded through its cylinder end by an air-blast through the respective ports, into the path of the lever next mentioned; a reciprocating slide to which the matrix-carrier is connected; and a bell-crank lever carried by the said slide and engaging with the protruded push-rod to engage the matrix-carrier and move it along its axis in one direction or to allow the said carrier to move in the opposite direction.

90

25. The combination in a type casting and composing machine, of an air-chamber kept charged with air under pressure; a series of discharge-ports therein; a series of ports respectively opposite the said ports; a space between the two series of ports adapted to pass the controller in air-tight contact with the respective surfaces, the controller having font-changing perforations adapted to coöperate with the said two series of ports; a multiple-font matrix-carrier adjustable for change of font in the direction of its axis.

of font in the direction of its axis; a series of cylinders respectively connected with the ports of the second series mentioned above and fitted with pistons and push-rods, a push-rod to be protruded beyond the respective cylinder end by an air-blast through the respective ports, into the path of the next-mentioned lever; a reciprocating slide to which the matrix-carrier is connected; a bell-crank lever carried by the said slide and engaging with the protruded push-rod to engage the matrix-carrier and move it along its axis for change of font; and a cylinder-block containing the above-mentioned cylinders and adapted to be moved by the continued motion of the above-mentioned slide after the latter has actuated the bell-crank lever.

26. The combination in a type casting and composing machine, of an air-chamber kept charged with air under pressure; a series of discharge-ports therein; a series of ports respectively opposite the said ports; a space between the two series of ports adapted to pass the controller in air-tight contact with the respective surfaces, the controller having font-changing perforations adapted to coöperate with the said two series of ports; a multiple-font matrix-carrier adjustable for change of font in the direction of its axis; a series of cylinders respectively connected with the ports of the second series mentioned above and fitted with pistons and push-rods, a push-rod to be protruded beyond the respective cylinder end by an air-blast through the respective ports, into the path of the lever next mentioned; a reciprocating slide to which the matrix-carrier is connected; a bell-crank lever carried by the said slide and engaging with the protruded push-rod to engage the matrix-carrier and move it along its axis in one direction or to allow the said carrier to move in the opposite direction for change of font; and a cylinder-block containing the above-mentioned cylinders and adapted to be moved by the continued motion of the above-mentioned slide after the latter has actuated the bell-crank lever.

27. In a type-casting machine, a mold consisting of two blocks held apart by a distance equal to the back-to-belly dimension of the type or space to be cast therein; a top plate held down fast upon the said blocks; a guide on the said top plate on which one of the said blocks can be moved up to or away from the other block; a pair of slides fitting between the two blocks to form the top of the mold and a platform to form the bottom of the mold and upon which the mold can move.

28. The combination in a type-casting machine, of a projection coöperating with the respective matrix; a mold; a mold-wall against which one side of the type or space is cast, adjustable to and from the opposite wall; means actuated by the said projection for adjusting the distance between the said walls of the mold for setway dimension of the respective body;

and means for adjusting the said means to meet the requirements of a substitute font.

29. The combination in a type-casting machine, of a projection coöperating with the respective matrix; a mold; a mold-top adjustable to and from the bottom of the mold for setway dimension; a bell-crank lever holding a nose in the path of the said projection to the casting position; a lever having the mold-top resting upon it; and a connection between the two levers adapted to raise the mold-top according to the length of the said projection. 75

30. The combination in a type-casting machine, of a projection coöperating with the respective matrix; a mold; a mold-top adjustable to and from the bottom of the mold for setway dimension; a bell-crank lever holding a nose in the path of the said projection to the casting position; a lever having the mold-top resting upon it; a connection between the two levers adapted to raise the mold-top according to the length of the said projection; and means for adjusting the said means to meet the requirements of a substitute font. 80 90

31. The combination in a type-casting machine, of a projection coöperating with the respective matrix; a mold; a mold-wall against which one side of the type or space is cast, adjustable to and from the opposite wall; means actuated by the said projection for adjusting the distance between the said walls of the mold for setway dimension of one side bearing; and means for adjusting the said means to meet the requirement of a substitute font. 95 100

32. The combination in a type-casting machine, of a projection coöperating with the respective matrix; a mold; a mold-top adjustable to and from the bottom of the mold for setway dimension of one side bearing of the respective body to be cast; a bell-crank lever holding a nose in the path of said projection to the casting position; a lever having the mold-top resting upon it; and a connection between the two levers adapted to raise the mold-top according to the length of the said projection. 105 110

33. The combination in a type-casting machine, of a projection coöperating with the respective matrix; a mold; a mold-top adjustable to and from the bottom of the mold for setway dimension of one side bearing of the respective body to be cast; a bell-crank lever holding a nose in the path of the said projection to the casting position; a lever having the mold-top resting upon it; a connection between the two levers adapted to raise the mold-top according to the length of the said projection; and means for adjusting the said means to meet the requirements of a substitute font. 115 120

34. The combination in a type-casting machine, of a mold-top consisting of a pair of slides capable of independent motion away from and back to the opposite side of the mold; a projection on the matrix-carrier; means actuated by the said projection to adjust the set- 125 130

way dimension of the mold; a shoulder on one of the said slides; and a projection on the matrix-carrier adapted to engage over the said shoulder and hold the last-mentioned slide down upon the said opposite side of the mold, to adjust the latter to cast spaces of less height to paper than the type-bodies of the same font.

35. The combination in a type-casting machine, of a mold-top consisting of a pair of slides capable of independent motion away from and back to the opposite side of the mold; a projection on the matrix-carrier; means actuated by the said projection to adjust the set-way dimension of the mold; a shoulder on one of the said slides; a projection on the matrix-carrier adapted to engage over the said shoulder and hold the last-mentioned slide down upon the said opposite side of the mold to adjust the latter to cast spaces of less height to paper than the type-bodies of the same font; and means for regulating the action of the above-mentioned adjusting means to vary the set-way dimension of the spaces to meet the requirement of the respective font.

25 36. In a type-casting machine, the combination of lever; a spring to rock it during the working stroke of the piston that ejects the type-metal from the metal-pot into the mold; a reciprocating slide; a lever pivoted thereto; and moving therewith; an incline up and over which the nose of the said lever moves to engage the first-mentioned lever and put its actuating-spring in tension; and a roller on the pivoted lever to also ride up the said incline to disengage the said nose from the respective lever when the respective matrix is in contact with the mold.

37. In a type-casting machine, and to regulate the quantity of type-metal ejected by one working stroke of the piston, a piston-rod capable of being screwed for a longer or shorter distance into its piston and a screw adjustable in the path of a lever rocking during that stroke toward the said screw.

45 38. In a type-casting machine, the combination of a drum-shaped matrix-carrier having projections from its periphery; a mold presenting the mold-cavity through a flat surface of the machine-frame; means for moving the matrix-carrier up to the said surface; an arc-shaped concavity in the said surface parallel with the axis of the matrix-carrier; and cavities in the mold to receive as many of the projections opposite to it, as are not for the time being coöperating with the mold.

39. In a type-casting machine, a series of trimming-knives comprising a knife for bending and shearing off the jet, one for trimming the bottom side of the type; one for trimming the foot; two for trimming off the fins from the back and belly, and means for presenting the type to them successively and pushing it past them.

40. In a type casting and composing machine, the combination of a type-race com-

prising a short vertical portion, a horizontal portion and an arc-shaped portion connecting the other two; a line-support adapted to receive the types as they are assembled in the race to form a line; means for retracting the 70 line-support; a column-support to receive the said line after the retraction of the line-support; a depressor to force the assembled line down upon the column-support; means for actuating it; means for returning both line support and depressor to their original position and mechanism actuated by the line-resistance slide to put all the above-mentioned means into action and out of action at the proper times.

41. In a type casting and composing machine, the combination of line-resistant and brake to control the return of the same, the said brake being locked out of action during the assemblage of a line, and unlocked by the said resistant when such assemblage is complete.

42. The combination with a type-race of fixed sectional area of a line-depressor having a spring-cushioned shoe adapted to support type being assembled in the said race against 90 being pied.

43. In a type casting and composing machine, the combination of type-race; a galley extending downward from the said race and curved toward the front; a column-support 95 adapted to slide up and down the said pulley; a counterpoise for the said support consisting of a lever, a weight thereon, a line arranged as a single whip and adapted by being fast by one end to the column-support and having its 100 other end in connection with the weighted lever, to increase the counterpoising effect of the weight as the lines of type accumulate on the column-support.

44. In a type casting and composing machine, the combination of type-race; galley extending downward from the said race and carried toward the front; a column-support adapted to slide up and down it; a counterpoise for the said support increasing in efficiency as the 105 lines of type accumulate upon the column-support; guides in the galley for the latter; and means for detaching it from the galley.

45. In a type casting and composing machine, the combination of type-race; galley extending downward from the said race and curved toward the front; a column-support adapted to slide up and down it; a counterpoise for the said support increasing in efficiency as the lines of type accumulate upon the column-support; guides in the galley for the latter; means for detaching it from the galley; and an abutment to limit the length of line.

46. In a type casting and composing machine, the combination of drum-shaped matrix-carrier equipped with various fonts and adapted to be moved about its axis for change of character and along the said axis for change of font; mold; means for advancing the matrix-carrier to the mold and retracting it; perfo- 130

rated - controller feed mechanism; series of slides; mechanism interposed between the controller feed mechanism and the series of slides for making the latter reproduce the perforations for the respective character; a rotating cylinder to provide for the return of the respective slides to their original position; connection between the said cylinder and matrix-carrier to turn the latter about its axis; means controlled by the perforated controller for adjusting the said matrix-carrier for change of font; mold; casting mechanism; ejecting mechanism; trimming-knives; and galley.

47. In a type casting and composing machine comprising a drum-shaped matrix-carrier equipped with various fonts and adapted to be moved about its axis for change of character and along the said axis for change of font; mold; means for advancing the matrix-carrier to the mold and retracting it; perforated-controller feed mechanism; series of

slides; mechanism interposed between the controller feed mechanism and the series of slides for making the latter reproduce the perforations for the respective character; a rotating cylinder to provide for the return of the respective slides to their original position; connection between the said cylinder and matrix-carrier to turn the latter about its axis; means controlled by the perforated controller for adjusting the said matrix-carrier for change of font; mold; casting mechanism; ejecting mechanism; trimming-knives; galley; and means for putting the said rotating cylinder out of action, to change the said machine to a type- casting machine.

In witness whereof I have hereunto set my hand in the presence of two witnesses.

JOSEPH PINEL.
